UNITED STATES PATENT OFFICE.

CHARLES LANE GOODRUM, OF ROCHESTER, NEW YORK, ASSIGNOR, BY MESNE ASSIGNMENTS, TO WESTERN ELECTRIC COMPANY, OF NEW YORK, N. Y., A CORPORATION OF ILLINOIS.

AUTOMATIC TELEPHONE SYSTEM.

1,147,389.

Specification of Letters Patent. Patented July 20, 1915.

Application filed July 22, 1907. Serial No. 384,940.

To all whom it may concern:

Be it known that I, CHARLES L. GOODRUM, of Rochester, in the county of Monroe and State of New York, have invented certain new and useful Improvements in Automatic Telephone Systems; and I do hereby declare the following to be a full, clear, and exact description of the same, reference being had to the accompanying drawings, forming a part of the specification, and to the reference-numerals marked thereon.

The present invention relates to automatic telephone systems and it has for its object to provide a system of this character which shall be full metallic in every particular requiring but two wires for each subscriber's instrument circuit over which current for talking and signaling purposes is transmitted as well as the necessary currents which are despatched to control the operation of movable switching mechanisms employed for connecting one subscriber's instrument circuit to another. The switching mechanisms referred to comprise generally finder and connector switches, the former operating automatically to pick up a calling line and the latter acting in unison with impulses of current subsequently transmitted over said line to select a particular line with which it is desired to establish a connection.

Another object of the invention is to provide mechanism coöperating with said finder and connector switches by means of which signaling current may be applied to the selected line to intermittently operate the calling devices or ringers at a called party's station.

The invention also comprehends the arrangement of apparatus to be used at the central office or exchange for the distribution of traffic over a plurality of switching mechanisms or groups of such mechanisms. In this connection certain switches are grouped in reference to one another and arranged for simultaneous operation, whereby two or more of them are started to pick up an instrument circuit on which a call has been originated, said switches coöperating with the circuit terminal in such a manner that the time required to select a given circuit is reduced to the minimum.

An additional attainment included in the invention is the means by which a busy test signal is automatically returned to a calling subscriber in the event an instrument circuit

with which he endeavors to obtain connection is otherwise in use, said means also including an arrangement of mechanism whereby either a calling or called subscriber, whose instrument circuits have been connected, may destroy said connection and either or both of them may separately obtain immediate connections with other subscribers' instruments.

The arrangement of the switching mechanism at the central office is also designed to enable a further object of the invention to be attained whereby the chief operator or clerk in charge thereof may be fully informed at all times regarding the operativeness of each switch. In carrying out this feature of the invention a signal such as a lamp is employed which may, for instance, be located at the operator's desk, the temporary lighting thereof indicating a call passing through a particular switch or group of switches and its continued illumination being an indication of improper operation due to some line trouble which by this aid may be readily located.

To these and other ends the invention consists in certain improvements and combinations of parts all as will be hereinafter more fully described, the novel features being pointed out in the claims at the end of the specification.

In the drawings: Figures 1 and 2 are diagrammatic views illustrating generically the line connection as it is effected between two instrument circuits by means of the finder and connector switches, the operating mechanism of the switches being omitted, the first view showing the positions of the switches in connecting instrument A with instrument B and the second illustrating the reverse connection. Fig. 3 is a diagrammatic view of a plurality of telephone instrument circuits, showing the actuating and cut-off relays associated with each line. Fig. 4 is a diagrammatic view (a continuation of Fig. 3) showing the arrangement of the terminals of said instrument circuits on a plurality of groups of finder and connector switches, with the traffic distributing mechanism controlling said groups of switches whereby two or more pairs of telephone instruments may be connected at the same time. In this figure the operating mechanisms of the switches have also been omitted. Fig. 5 is a diagrammatic view illustrating a

finder switch in conjunction with a plurality of instrument circuits illustrating the controlling mechanism by means of which an instrument circuit on which a call is originated may be extended to the connector switch. Fig. 6 is a similar view of the connector switch showing the controlling mechanism by means of which said switch wipers are operated to select the terminals of the circuit of another telephone instrument to connect it to the extended instrument circuit shown in Fig. 5. Fig. 7 is a view similar to Fig. 5, illustrating in addition to the finder switch, a traffic distributor switch mechanism and a signaling switch mechanism. Fig. 8 is a complete assembled view of the mechanism employed in conjunction with the connector switch showing the various mechanisms and the circuits controlling them by means of which the switch wipers are advanced progressively in one direction into an operative position and are released to restore them to their normal position, in conjunction with the devices employed for despatching signaling current over a selected instrument circuit, the devices for despatching the busy signal, which are operated in the event that a selected instrument circuit is connected through some other switch, or group of switches, and the apparatus which is actuated when the subscriber on the selected line answers in. Fig. 9 is a detail diagrammatic view of the motor magnet circuit of the connector switch. Fig. 10 is a similar view of the circuits established, when a particular line has been selected by the connector switch, to automatically despatch the signaling current over said line. Fig. 11 is a similar view illustrating the circuits over which the busy test is obtained. Fig. 12 is a detail diagrammatic view showing the release circuits of the finder and connector switches which illustrates the conjoint operation of the release mechanism of said switches. Fig. 13 is a diagrammatic view showing the method of arranging the associated finder and connector switches in duplicate sets, to facilitate the picking up of incoming lines for the purpose of minimizing the length of time required to establish a connection and also to insure the connection being made, in case one set of switches fails to perform its proper functions. Fig. 14 is a plan view illustrating a type of switch which may be employed as finder, connector, distributing or signaling switches for operation with this system. Figs. 15 and 16 are detail sectional views thereof taken on the lines 15^x—15^x and 16^x—16^x respectively.

To facilitate tracing the circuits referred to in the following specification, Figs. 3 and 4 should be placed together, the former above the latter; Figs. 5 and 6 should be joined, the former at the right hand side of

the latter; and Figs. 7 and 8 should be similarly considered. The skeleton diagrams shown in Figs. 9, 10, and 11 inclusive, are reproductions of circuits also shown in Fig. 8.

70

Similar reference numerals in the several figures indicate similar parts.

In a telephone exchange system embodying this invention the connections between different telephone lines are automatically set up, or effected, by apparatus arranged at the central office or exchange, and the telephone lines or circuits leading thereto are divided into two classes comprising, first, incoming lines, or those on which calls are originated by subscribers who desire to establish communication with other parties, and, secondly, outgoing lines over which the calls are despatched to signal said parties. Each line may, at different times, be of either class and it will, therefore, be understood when these lines are referred to in the following description, that an incoming line or calling circuit is one leading from a subscriber's telephone or station over which impulses of current are sent to connect said line to an outgoing line and that the latter is the called circuit on which the signaling devices are actuated, when the connection has been set up or completed between the telephone instruments of the calling and the called subscribers.

In the system embodying the present invention it is possible to connect by means of the central office, or exchange, apparatus a given line with any other line and to this end all the lines lead to terminals on a finder switch, or a plurality of such switches, and to similar terminals on an associate connector switch or switches. The finder switch performs the function of selecting an incoming line on which a call has been originated, and the connector switch, associated therewith, performs a similar function in selecting the outgoing line leading to a particular telephone instrument, or subscriber's station, with which the calling subscriber desires to communicate. The movable elements or wipers of the finder switch and its associate connector switch are tied together, so that when the functions of each have been performed, the talking circuit, from the incoming to the outgoing line, is extended through them and may be retained until one of the two communicating subscribers desires to effect a disconnection of said lines.

In Figs. 1 and 2 the above described connections are shown diagrammatically, two separate instruments being shown in each, and indicated generally by A and B, with a single finder switch F and a single connector switch C. In Fig. 1, the movable elements or wipers of the two switches are shown in a position illustrating the connection estab-

lished from instrument A to instrument B when the circuit of the first mentioned instrument is the incoming line on which a call is originated, and in Fig. 2 these parts 5 of the switches are shown in the position which they occupy when instrument B is the one on which a call was initiated.

The telephone instruments may be of the usual or any preferred construction comprising generally a transmitter 1, a receiver 2, and the signaling devices or bells 3, all of which are arranged in the circuit of the line wires A'—A² of instrument A, and B'—B² of instrument B. The instrument circuits 10 are normally open at each subscriber's station at the contacts A³—B³ which are controlled by the receiver hook and are closed when the latter is released by the subscriber removing his receiver therefrom. Each pair 15 of wires constituting the circuits of the telephone instruments is extended to the aforementioned switches located at the central office and terminate in immutable contacts located thereon, those of the wires A'—A² 20 being located on the switch F, as indicated by A¹⁰—A²⁰, the corresponding contacts on the switch C being indicated by A¹¹—A²¹, said contacts being tied together by conductors A¹²—A¹³ the similar contacts of the 25 wires B'—B² on the switch F are indicated by B¹⁰—B²⁰ and on the switch C by B¹¹—B²¹, said pairs of contacts being also tied together by wires B¹²—B¹³. The operating 30 mechanisms controlling the movable elements or wipers of the two switches have been omitted from these illustrations but, as will appear more fully hereinafter, they are 35 designed to cause such switches to move progressively over a bank of contacts or terminals, representing a large number of telephone 40 lines. The wipers of the switch F are indicated by F'—F² and those of the switch C by C'—C², the corresponding wipers of the two switches being connected 45 by wires 4 and 5.

From an inspection of Fig. 1 it will be seen that the complete circuit between the instruments A and B may be traced as follows: instrument A, wire A', contact A¹⁰, 50 wiper F², wire 5, wiper C², contact B¹¹, wire B', instrument B, wire B², contact B²¹, wiper C', wire 4, wiper F', contact A²⁰, wire A², instrument A. The foregoing is predicated upon the fact that the call originated at the 55 instrument A and the mechanism of the finder switch operated to pick up the contacts of the incoming circuit A'—A², after which the switch C was actuated to connect said circuit with the terminals of the outgoing line B'—B². Supposing a reverse operation to be effected in a like manner. The 60 movable elements of the finder switch F traverses its bank of contacts, or terminals, until reaching the terminals B¹⁰—B²⁰ of the line B'—B² then the connector switch C op-

erates to pick up the terminals A¹¹—A²¹ of the line A'—A². The circuit between the two telephone instruments will then be traced as follows: instrument B, wires B², B¹³, contact B²⁰, wiper F', wire 4, wiper C', contact A²¹, wires A¹³, A², instrument A, wires A', A¹², contact A¹¹, wiper C², wire 5, wiper F², contact B¹⁰, wires B¹², B', instrument B.

The switches.—In illustrating the mechanism by means of which connections between the lines are effected, a type of switch adapted for this purpose is shown in Fig. 14, details thereof being shown in Figs. 15 and 16. This switch is capable of performing the functions of either the finder, connector, distributing or signaling switch, the only difference being in the number of brushes or wipers employed and the manner of wiring the contacts in their respective banks, as will be fully explained hereinafter in connection 85 with the diagrammatic illustrations.

The switch proper comprises generally a progressively movable member 6, which is adapted to be advanced step by step, and to this end is made circular in form and is 90 mounted upon a revoluble shaft 7 journaled at its lower end in the base plate 8, and supported at its upper end by a bearing on a bracket 9, the ends of which extend downwardly and are secured to the base plate, 95 as shown in Fig. 16. Carried on the movable member and insulated therefrom are contact elements or spring wipers 10 and 11, corresponding to the wipers F'—F², of the switch F, and C'—C², of the switch C. 100 These elements are arranged one below the other and their outer ends are adapted to cooperate with a series of insulated terminal contacts 12 and 13, arranged in pairs corresponding to the contacts A¹⁰—A²⁰, etc., 105 those of each pair being located in vertical alinement, as shown in Fig. 15. As each switch controls a plurality of telephone lines, these pairs of terminals are supported upon a segmental bridge 14, and are 110 arranged concentric with the center of movement of the wipers. Beneath said contacts are other contacts 15 and 16 with which cooperate wipers 17 and 18, the purpose of all of which will be subsequently described, 115 but it may be here stated that the usual terminal contacts 12, 13, 15 and 16 are arranged in sets, each set being devoted to a single incoming instrument circuit, there being four contacts on the finder switch and 120 three on the connector switch. The rear end of each wiper is provided with a segment, as indicated by 10^a, 11^a, 17^a, 18^a, with which, coöperate brushes 10^b, 11^b, 17^b, 18^b, supported in a holder 19, of insulating 125 material, secured to one of the ends of the bracket 9. Connected to the lower end of the shaft 7 is a coil spring 20 to which sufficient tension is applied to return the shaft and the parts supported thereon to their 130

normal position when they are released, as shown in Fig. 14.

The operating devices for advancing the movable elements or wipers comprise a pawl 21, pivoted to the upper end of an arm 22 on which it is moved by a spring 23 into engagement with teeth 24 on the periphery of the member 6. The arm 22 is pivoted at the point 25 and is provided with a laterally extending end 26, forming an armature, co-operating with the motor magnet 27, which armature is normally held in retracted position by the spring 28 bearing against the stud 29 on the arm 22, said spring also serving to advance the member 6 when the pawl 21 is in engagement therewith. A spring operated detent 30 serves to lock the movable element in adjusted position and at its outer end is a finger 31, projecting beneath the end of the pawl 21, the arrangement of the parts being such that when the pawl is moved downwardly into an inoperative position the detent will be retracted, as shown in Fig. 14. The means for effecting the release of the member 6 comprises a spring latch member 33 having an end 34 which is adapted to hook over the edge of a lip 32 depending from the pawl 21. At its lower end the spring 33 is attached to an armature 35, pivotally supported in proximity to the release magnet 36, carrying an upwardly extending arm 37 provided with a stud 38 with which co-operates a spring 39 normally tending to move the arm in a direction to retract the armature 35. Supported upon the base plate 8, in front of the spring 33, is a stud 40, which limits the lateral movement of the spring when the armature 35 is retracted, thereby permitting the lip 32 of the pawl to be disengaged from the hooked end of the spring, when said pawl is retracted by the energizing of the motor magnet 27. The movable member 6, controls two circuits, as will be further described in connection with the diagrammatic illustrations, which include a contact spring 41 playing between contact members 42 and 43, supported in a holder 44, on the base plate 8. The spring 41 has a normal tendency to engage the contact 42, but is held in engagement with the contact 43, when the member 6 and the contact elements carried thereon are in their normal position, by a pin 45 mounted on the member, which releases said spring upon the first step or movement imparted to said member.

The base on which the switch mechanism is mounted is composed of the part 8^a supporting the bridge 14 and the part 8 carrying the operating devices and which may also be utilized as a support for relays operating in conjunction with the motor and release magnets. The parts of the switch base are detachable, the portion 8^a

being adapted to be rigidly connected to a suitable switch board frame and comprising side pieces between which the forward end of the part 8 is guided to insure the proper centering of the shaft 7 relatively to the arc of the bank of contacts. This construction permits the operating mechanism to be readily removed for inspection or adjustment of its parts which is an advantageous feature in apparatus of this character because it is customary to arrange a large number of these switches compactly in rows and tiers to economize space, so that unless the working parts are removable considerable difficulty is experienced when it becomes necessary to correct some fault in their operation.

The finder and connector switches are actuated by electromagnetic devices peculiar to each, those of the finder switch being automatically set into operation, and controlled by secondary circuits, which are established when an instrument circuit is closed at the subscriber's station, and the mechanism of the connector switch is rendered operative when the finder switch has picked up the incoming or calling circuit and is controlled by impulses of current which may be despatched by a suitable form of impulse transmitter located at the subscriber's station, to select a given outgoing line, or called circuit. Accordingly the instrument circuit, comprising wires A'-A², is extended, as indicated at A¹⁴, A²⁴, Figs. 1, 2, 3, 5 and 7, to normally closed contacts A⁴¹-A⁴², one of which is mounted upon a spring finger provided with a projection 46 adapted to co-operate with teeth on an impulse transmitter A⁴ to thereby transmit or send over the operating circuit one or more impulses of current, when the circuit is closed at the hook contacts A³.

The electromagnetic mechanisms for causing the various switches to perform their respective functions, are all adapted to be operated from a common battery, but in order to facilitate the description and illustration, and render a more comprehensive understanding of the various circuits to be had, these are shown in the various diagrammatic views as receiving current from different sources or sets of batteries Z'-Z², etc. To render the circuits easy to trace they are shown with the conventional ground or earth connections, but it will be understood that where the term ground is employed and shown, it refers to a connection leading directly to one side of the main battery, so that a telephone system embodying this invention, when installed in working order, is entirely free of the so-called grounds employed for actuating parts of the apparatus, thereby eliminating line disturbances or other troubles attributable to this cause.

Traffic distribution.—The simplest phase

of the system has been explained in connection with Figs. 1 and 2, but as such an arrangement of parts only permits intercommunication between two subscribers at the same time, it is desirable to provide a plurality of groups of associated finder and connector switches, on each of which appear the terminals of all instrument circuits, and to combine with said groups a distributing mechanism by means of which two or more subscribers may connect their telephone instruments in pairs and carry on private conversation with each other. This grouping of the switches is illustrated in Fig. 4, which shows three sets of finder and connector switches, said groups being indicated by I, II and III. The corresponding terminals of each instrument circuit appear in the banks of contacts of all of the finder and connector switches and are connected by the trunk lines in the manner illustrated in Fig. 4. These trunk lines are ramifications or branches of the instrument circuits, such as those shown in Fig. 3, and although only three groups of switches have been shown, it will be understood that the number of these may be increased in reference to the total number of lines served and the percentage thereof which it may be desired to accommodate at one time. It has been determined from actual practice that the number of calls received at any one time does not, as a rule, exceed ten per cent. of the total number of telephone instruments. Any desired number of groups of finder and connector switches, may be installed so that a given ratio of calls may be accommodated at the same time, successive calls being put through different groups of switches by the traffic distributing mechanism, as will appear more fully hereinafter.

To illustrate the above described grouping of switches and the distribution of calls thereover in a graphical manner, six telephone instrument circuits have been shown in Fig. 3, which are indicated respectively by A, B, G, H, I, J. Instruments A and B in Figs. 3 and 4, are shown with the same circuits illustrated in Figs. 1 and 2, and the circuits of the other instruments are identical therewith and are indicated by appropriate reference characters, both capitals and small letters, provided with proper exponents, so that detailed description of these may be omitted. From an inspection of Fig. 4 it will be seen that the contact banks of each finder and connector of each group contain terminals for all of the instrument circuits which are joined by the trunk connections, such as A¹², A¹³, B¹², B¹³. In group I, of this figure, the instrument A is connected to instrument B, in the same manner as shown in Fig. 1. Group II shows instrument H connected to instrument G, the terminals H¹⁰ and H²⁰ being engaged by the

brushes of the finder switch and the terminals G¹¹, G²¹ of the circuit of instrument G, being engaged by the brushes of the associate connector switch. In group III the brushes of the two switches are each shown in their normal position in readiness to connect a third pair of instrument circuits, permitting the subscribers of instruments I and J to communicate with each other during the time the connections on groups I and II are maintained. In effecting the aforescribed connections, the traffic distributing mechanism was brought into play and through it the operating mechanism of the finder switch of the first group I was automatically started in search of the terminals on which the incoming call was despatched. The distributor mechanism then advanced into position to actuate, in a like manner, the operating devices of the finder switch of the second group II, allowing the wipers of this switch to traverse their bank of contacts to engage the terminals of the line sending in the second call. Following this last operation the traffic distributor advanced in readiness to subsequently actuate the remaining group of switches III, upon receiving a call originated on any line. The third call might be despatched from either instruments I or J, or if the switches of group I should be released and either subscriber A or B attempted to establish another connection, it would be effected over the switches of group III.

The traffic distributing mechanism indicated by D, is illustrated generally in Fig. 4, but as its operation is dependent upon the operation of the finder and connector switches, it will be referred to more particularly hereinafter.

The finder switch.—To enable a comprehensive understanding to be had of the various features of the invention, it will be advantageous and facilitate an understanding of the system to first take up the various steps performed in connecting two instrument circuits over a single group of switches, it being understood at the outset that this operation is precisely the same on each group, the only difference being that said groups are operated successively by the movements occurring in the traffic distributing mechanism. One group of switches corresponding to the group I, shown in Fig. 4, is illustrated in the combined views Figs. 5 and 6, the former illustrating the finder switch mechanism and the latter that part of the connector switch by means of which it may be actuated by impulses of current despatched from a subscriber's instrument to select the terminals of another circuit.

In Fig. 5 the circuits of telephones A, B and J have been reproduced, with each of which is associated actuating relays A⁵, B⁵ and J⁵, respectively, which are arranged at

the central office and are adapted to be energized when their respective instrument circuits are closed to start the operation of the distributor D and the finder switch F, but to simplify the description at this point the distributor has been omitted and for the time being the finder switch will be described as being actuated directly by the closing of one or another of the instrument circuits.

10 Also associated with each of the latter are the cut-off relays A⁶, B⁶ and J⁶, the function of which is to restore the corresponding actuating relays to their normal position when the finder switch has picked up the calling instrument circuit. In Fig. 5 the finder switch is shown with a plurality of sets of the four terminal contacts arranged in rows, as shown in Fig. 15, those constituting the lower pair of the set related to the circuit of instrument A being indicated by f¹⁵ and f¹⁶. Leading from the contact f¹⁵ is a wire A¹⁵ connected to one end of the cut-off relay A⁶, the other terminal thereof being supplied at certain times with current from the battery Z²; another wire A¹⁶ leads from the contact f¹⁶ to a back contact a⁵ with which the armature a⁵ of the actuating relay normally engages, said armature having a grounded connection z⁴. One end of the 20 coil of the actuating relay A⁵ is connected to the battery Z² and its other extremity is connected to a back contact a² with which normally engages the armature a⁶ of the cut-off relay, said armature being connected to 25 one side of the instrument circuit by a wire a³ joined to the wire A². A second armature controlled by the cut-off relay, indicated by a⁴, is connected by a wire a⁷ to the other side A' of the instrument circuit. This armature normally engages a back contact a⁸ 30 also grounded at z⁴.

35 It has been explained in connection with Figs. 14, 15 and 16 how the movable contact elements coöperate with the several terminals of the bank of contacts of each set, but in Figs. 5 and 6 the illustrations are simplified by showing the circuit wires connected directly to the wipers, while in reality they are connected to brushes such as 10^b, etc., shown in Fig. 16. Referring now particularly to Fig. 5, it will be seen that the brushes F', F² are extended by the wires 4 and 5 through normally closed contacts on armatures of a relay F³ which will be described more fully hereinafter, the function ascribed thereto being that of opening the extended instrument circuit during the rotation of the brushes of the finder switch in one direction, to pick up an incoming line, 50 and when they are returning in the opposite direction, to their normal position. The opening of the ties between the switches eliminates any vibration in the receiver of a subscriber's telephone, as said brushes rotate over the coördinate contacts of other instru-

ment circuits which may have been previously connected over another group of switches, and it also prevents any possible interference with the mechanism of the associate connector switch during the operation of its finder switch.

Operating conjointly with the motor magnet 27^F is a relay F⁵, which performs the function of temporarily closing the holding circuit of the motor magnet; actuating the 75 relay F³; opening a circuit of one of the switch wipers, to prevent the actuation of the cut-off relays until the calling line has been found; and, also, to open the circuit of a switching relay, which has not been before 80 mentioned, and is associated with the connector switch. The operating circuit of the motor magnet is a secondary circuit over which current is supplied to cause its continuous operation until the wipers of the 85 switch F have picked up the incoming line. The finder switch mechanism is adapted to be operated whenever one of the instrument circuits is closed and to continue its movement to progressively advance its contact 90 elements or wipers until they pick up the terminals of said instrument circuit and to this end its mechanism is adapted to be started by a single impulse of current, caused by closing one of the instrument circuits, 95 after which it receives current over the secondary operating circuit. The starting of the switch is effected by a booster line f which is common to all of the instrument circuits and at one end has branches terminating in back contacts, such as f⁶ with which the armature a⁵ engages when the actuating relay A⁵ is energized. The other extremity of the booster line, indicated by f¹⁰⁰, terminates in the spring controlled 100 switch arm f⁴¹ which is normally held in engagement with the back contact f⁴² by the pin f¹⁵, said contact being connected by the wire f' to a terminal f², with which coöperates the armature f³ actuated by and arranged in the circuit of the motor magnet 27^F, to one end of the coil of which it is connected by the wire f⁴, the other extremity of said coil being supplied with current from the battery Z⁴. The booster line or 110 starting circuit also includes the relay F⁵ to which it is extended by the wire f⁵, said relay receiving current from the battery Z⁵ over the wire f⁷. The secondary operating circuit for the motor magnet leads over the wire f⁸ to a back contact f⁹, with which coöperates an armature f¹⁰, on the relay F⁵, connected by the wire f¹¹ to the switch wiper f¹⁸.

The relay F⁶ (similar to relay F⁵) is associated with the release magnet 36^F and is adapted to operate in conjunction therewith and with the release magnet of the associated connector switch C whereby both switches may be simultaneously released and 120

restored to their normal positions, although a description of the full release operation of the finder switch must necessarily be deferred until after the operation of the releasing mechanism of the connector switch has been explained. The coil of the release magnet 36^F is connected to the battery Z⁴ by the wire f¹² the other end thereof being extended by the wire f¹³ to an armature f¹⁴ on the connector switch, shown at the upper left-hand side of Fig. 6. The release magnet relay F⁶ is connected to the wire f⁷ by a wire f¹⁵, and by the wire f²⁰ to a forward contact f²¹ with which coöperates an armature f²², on the magnet 36^F, joined by the wire f²³ to ground z⁵. As the line opening relay F³ is adapted to be energized whenever the relays F⁵ and F⁶ are actuated, one end of its coil is connected by the wire f²⁴ to the battery Z⁵ and its other extremity is provided with the wire f²⁵ terminating in forward contacts f²⁶ and f²⁷, of armatures f²⁸ and f²⁹, which are adapted to be attracted by the relays F⁵ and F⁶, each of said armatures being connected to grounds z¹, z⁵ corresponding to the batteries Z¹ and Z⁵ respectively.

In connection with the circuits for releasing the finder switch, the spring controlled switch arm f⁴¹ coöperates with a back contact f⁴² grounded, as indicated at z¹⁵, which completes a circuit whereby said switch is automatically released if the finder switch is moved out of its normal position manually or by any other influence except the motor magnet. The third wiper f¹⁷ is connected by a wire f³⁰ to a back contact f³¹ of the armature f²⁸ by means of which the several cut-off relays may be energized at proper times.

The foregoing description has been confined to the parts of a single telephone circuit, but it will be understood that each finder switch F serves a comparatively large number of instrument circuits with each of which is associated the previously described actuating and cut-off relays. The wires A' and A² and the local wires A¹⁵ and A¹⁶ of the several telephone circuits are connected to the respective terminals of each tier in the bank of contacts, such as those indicated by 12, 13, 15 and 16 in Fig. 15.

All of the instrument circuits, when not in use, are normally open at the receiver hook contacts, such as A³, and as the movable contact elements or wipers of the finder switch, under such conditions, are in inoperative position, the spring switch f⁴¹ is retained in engagement with its back contact f⁴³.

In Fig. 5 an additional telephone circuit, indicated by J, has been illustrated to facilitate an understanding of the movement of the finder switch. This subscriber's set comprises the actuating relay J⁵, operating the armature j⁵ which is grounded as at z¹⁴, and

coöperates with the back contact j¹⁵ connected by the local wire J¹⁶ to the terminal j¹⁶ on the switch F. The circuit of the cut-off relay of this set, indicated by J⁶, includes the wire J¹⁵ leading to the contact j¹⁵ on the switch F. In the illustrations the terminals j¹⁵ and j¹⁶ are purposely located in front of the terminals f¹⁵ and f¹⁶, with reference to the direction of rotation of the wipers of the finder switch, to enable a comprehensive description of the circuits successively established by the movement of the switch wiper.

Automatic operation of the finder switch.—When the subscriber at station A removes his receiver and closes the contacts A³ the following circuit is established: instrument A, wires A², a³, armature a⁶, contact a², relay A⁵, battery Z², contact a⁸, armature a⁴, wires a⁷, A', instrument A. The energizing of the actuating relay attracts the armature a⁵, completing the following booster line or starting circuit: ground z⁴, armature a⁵, contact f¹, wires f, f¹⁰⁰, spring f¹¹, contact f⁴³, wire f', contact f², armature f³, wire f⁴, magnet 27^F, and battery Z⁴ to ground. At the same time the motor magnet relay F⁵ receives an impulse of current over the circuit comprising, in addition to the foregoing, wire f⁵, relay F⁵, wire f⁷, battery Z⁵ to ground.

The foregoing booster line or starting circuit is in part common to every instrument circuit leading to the finder switch and coöperates with all of the branches connected to the spring f¹¹, any one of which may be closed by its respective actuating relay to primarily actuate the motor magnet when the switching mechanism is in its normal position. The first impulse of current transmitted over the motor magnet 27^F causes the movable member of the switch to be advanced one step, permitting the spring switch f⁴¹ to disengage the contact f⁴³ and cause the contact elements or wipers to engage the first tier of contacts of an incoming line, for instance, those of the instrument B, but as the relay F⁵ was also energized, the armature f¹⁰ was attracted to complete the following circuit: battery Z⁴, magnet 27^F, wire f⁴, armature f³, contact f², wires f¹, f³, contact f⁹, armature f¹⁰, wire f¹¹, wiper f¹⁸, contact b¹⁶, wire B¹⁶, contact b¹⁵, armature b⁵, ground z¹⁴. It should be stated at this point that the cores of the relays F³, F⁵ and F⁶ are provided with a copper jacket or otherwise constructed to render their operation sluggish, consequently the relay F⁵ does not release the armature f¹⁰ the moment the armature f³ is attracted by the motor magnet 27^F. For this reason it will be seen that the difference in the time constants of this magnet and its associate relay permits the armature f³ of the former to continue its vibrations until the relay F⁵ is deenergized. The second and successive

steps imparted to the movable elements of the finder switch are caused by successively completing the operating circuit of the motor magnet and the holding circuit of the 5 slow relay F^5 , as the switch brushes traverse the bank of contacts and step from one set of terminals to another. As both of these circuits are completed through the brush or wiper f^{18} they are common to all of the 10 instrument circuits connected to the finder switch, and the local wires, such as A^{16} , B^{16} , J^{16} , constitute branches of said circuits which are controlled by the actuating relays of the respective instrument circuits. All 15 of the operating circuit branches are normally closed or connected to one side of the battery when the actuating relays are de-energized, while the starting circuit branches are all opened. Consequently, the energiz- 20 ing of the line relay reverses the condition of the branches under its control, that is, it closes the booster line or starting circuit and opens the operating circuit, so it will therefore be seen, that each time the wiper 25 f^{18} passes onto a contact grounded as at z^{14} , an additional impulse of current is given to the motor magnet of the switch, causing its movable elements to continue to advance until the wiper f^{18} reaches the terminal of 30 the operating-holding-circuit branch belonging to the incoming line on which the call was originated, when the switch will be arrested, because said circuit branch has been opened at the actuating relay armature. 35 This is shown in Fig. 5, in which the armature a^5 was held out of engagement with the contact a^{15} by the actuating relay A^5 , which was energized when the circuit of instrument A , the calling line, was closed. 40 The cessation in the flow of current in the circuits of the motor magnet 27^F and its relay F^5 permits the armatures on the latter to restore, or drop back, to their normal position, thus permanently breaking the operating 45 circuit at the contact f^9 . At this time the wiper element f^{17} is in engagement with the terminal f^{15} completing the following circuit: battery Z' ; cut-off relay A^6 , wire A^{15} , contact f^{15} , brush f^{17} , wire f^{30} , contact f^{31} , 50 armature f^{28} , ground z' , causing the armatures a^4 and a^6 to be pulled up to clear both sides of the telephone instrument circuit to disconnect it from the battery Z' . This de-energizes the actuating relay A^5 allowing 55 its armature to be restored to the normal position (shown by full lines in Fig. 5), sub-sequent to the restoring of the armature f^{10} , on the relay F^5 , to complete a circuit leading to the switching relay, or primary controller 60 S (Fig. 6), which renders the connector switch capable of operation when the finder switch has completed its function.

The connector switch.—The connector switch comprises apparatus common to all 65 the incoming lines which is rendered opera-

tive as soon as the finder switch has selected the particular line on which a call has been originated. The movement of this switch is controlled by mechanism which is actuated by impulses of current despatched in any 70 suitable manner, but preferably by an impulse transmitter, such as that indicated by A^4 , located at the subscriber's station. This mechanism has for its primary object to control the operation of the movable contact 75 elements or wipers C' , C^2 to permit their adjustment into engagement with the terminal contacts of any instrument circuit on said switch, and further, to render the circuit so connected (the outgoing called line) 80 engaged or busy to prevent the called subscriber from attempting to set up a different connection through these finder and connector switches F and C at this time. Additional devices are incorporated with the 85 mechanism controlling the connector switch, whereby after a called party has answered in he may destroy the connection and establish another connection over a different group of switches with a third subscriber's 90 line. These additional devices also include means for automatically despatching to a calling subscriber, what is termed a busy signal in case the line of the party with whom he desires to communicate is other- 95 wise in use. The busy signal is produced by means of current supplied by the generator employed for furnishing signaling current and comprises apparatus for producing a buzzing sound, or humming tone, in the re- 100 ceiver of the calling party when the wipers or movable contact elements of a connector switch of one group engages the coördinate contacts of an outgoing or called line which is connected through the brushes of some 105 other connector switch belonging to another group of switches. Inasmuch as the signaling is not effected until after the connection has been completed over the connector switch and the busy signal is not returned unless 110 the selected party's line is engaged, and none of these operations are perfected until after the controlling devices of the connector switch have performed their operation, these parts are illustrated in separate views and 115 Fig. 6 is, therefore, devoted to those parts of the apparatus whose function is to cause the progressive movement of the wipers or contact elements of the connector switch.

Among those persons versed in this art it 120 is customary to designate the two conductors of the telephone circuit (such as A' , A^2 , 4, 5 and 4^A , 5^A), as the line and mate wires and as these expressions will serve to elucidate further description, this nomenclature will 125 be adopted.

In tracing the circuit from the switch F to the switch C it will be seen that the line and mate wires 4 and 5 leading from the brushes F' and F^2 (Fig. 5), are extended as indi- 130

cated by 4^A and 5^A (Fig. 6) to the wipers C' and C² of the switch C and have interposed therein condensers 47 and 48. The line and mate conductors 4 and 5, 4^A and 5^A form the tie between the finder and connector switches and leading from these conductors are branches 40^A and 50^A, each of which is connected respectively to one end of the coil of the line and mate relays 41^A and 51^A, said coils being arranged in tandem, thereby serving to balance the line. The other ends of the coils of these relays are connected to opposite sides of the battery Z, the current from which causes both the line and mate relays to be energized when the brushes F' and F² of the finder switch F are in coöperative engagement with the terminals of the incoming line. These tandem coils are associated with the motor magnet 27^C and indirectly they also control the release magnet 36^C of the switch C in the performance of their respective functions.

Motor magnet operation of connector switch.—The motor magnet 27^C is adapted to respond in unison to successive impulses of current transmitted to the line and mate relay coils, and to be rendered inoperative, after a given number of such impulses has been sent, to prevent its subsequent operation. In order to accomplish this object a peculiar combination of relays is employed which operate in conjunction with the line and mate relays, three of such relays being used in the present instance each of which is so constructed as to render its operation slow or sluggish, to give them time constants of less value than the line and mate relay coils, whereby contacts controlled by these three relays may be closed and held in this position during the movement of other armatures vibrated by successive current impulses in the line and mate relay coils. One of these three relays, indicated by C³, may be termed, for convenience in description, an assistant line relay, as it has for its function the closing of the circuits of the remaining two relays; the closing of one opening in the motor magnet circuit; and the opening of the release magnet circuit. One of the remaining two relays, indicated by X, closes another opening in the circuit of the motor magnet and the other, indicated by Y, completes a secondary or holding circuit of the relay X whereby the latter is retained in energized condition to hold said opening in the motor magnet circuit closed during its continuous operation. Both of these relays are deenergized upon the cessation of movement of the motor magnet, the relay Y breaking the circuit of the relay X and the latter destroying the motor magnet circuit and as the relays X and Y can only be energized when the switch C is in its normal position it becomes impossible to subsequently energize the motor magnet after it has once

ceased its operation in response to a given number of impulses. The above mentioned parts are shown in Figs. 6 and 8 and illustrated in detail in Fig. 9.

The assistant line relay C³ receives current from the battery Z⁶ by the wire c' and the other side of its circuit, indicated by c², is normally open at the contact c³ with which the armature c⁴ coöperates, said armature having a grounded connection z⁶. One end of the coil of the motor magnet 27^C is extended by the wire c⁵ to the forward contact c⁶ of an armature c⁷ on the relay X, which is connected with the battery Z⁷ and the other extremity of said coil is extended by the wire c⁸ to a back contact c⁹ of an armature c¹⁰ from which leads the wire c¹¹ to a forward contact c¹² of an armature c¹³, located on the relay C³, having a grounded connection z⁷. A wire c¹⁴ leads from the relay X to a back contact c¹⁵ with which the spring switch arm c⁴¹ is held in normal engagement by the pin c⁴⁵, said spring being grounded as indicated at z⁸. The remaining portion of the starting circuit of the relay X comprises the wire c¹⁵ terminating in a forward contact c¹⁸ of an armature c¹⁹ on the relay C³ which receives current over the wire c²⁰ from a battery Z⁸. Tracing the foregoing circuits shows that the energizing of the tandem coils 41^A and 51^A attracts the armatures c⁴, c¹⁰, the former closing the following circuit: (Fig. 9) battery Z⁶, wire c', relay C³, wire c², contact c³, armature c⁴, ground z⁶. The energizing of the relay C³ attracts the armatures c¹³ and c¹⁹, completing the following starting circuit: battery Z⁸, wire c²⁰, armature c¹⁰, contact c¹⁸, wire c¹⁵, relay X, wire c¹⁴, contact c¹⁵, spring switch arm c⁴¹, ground z⁸. Thus the relay X is energized and two openings in the motor magnet circuit are closed by the attraction of the armatures c⁷, c¹³, so that each time the line and mate relay coils 41^A, 51^A are deenergized and the armature c¹⁰ is permitted to engage the contact c⁹, the following circuit is established: battery Z⁷, armature c⁷, contact c⁶, wire c⁵, magnet 27^C, wire c⁸, contact c⁹, armature c¹⁰, wire c¹¹, contact c¹², armature c¹³, ground z⁷. In order to retain the magnet X energized, after its starting circuit has been broken, upon the first step of the wipers of the connector switch, by the disengagement of the spring switch arm c⁴¹ from the contact c⁴⁵, the relay Y is brought into service. The circuit of the latter comprises the wire c²¹, connected to the wire c⁵, and the wire c²² connected to the wire c¹¹. This circuit is normally open at two places which are closed by the action of the relay C³ and X to complete the following circuit: battery Z⁷, armature c⁷, contact c⁶, wire c²¹, relay Y, wires c²², c¹¹, contact c¹², armature c¹³, ground z⁷. On the relay Y is an armature y

connected by a wire x' to the wire c^{14} and coöperating with a forward contact x^2 joined by the wire x^3 to an armature x^4 , on the mate and line relay coils, which normally engages a back contact x^5 connected by the wire x^6 to the wire c^{11} . It will be remembered that the extension of the closed calling instrument circuit by the switch F caused the tandem coils constituting the line and mate relays to be energized, this closed the circuit of the relay C³, the latter energized the relay X, which in turn closed the circuit of the relay Y. It is reiterated that the relays C³, X and Y are slow or sluggish in their operation so that the residual magnetism in their coils will cause their respective armatures to be held in attracted position while the armatures on the line and mate relay coils are vibrated with a given regularity. Each time the armature x^4 engages the contact x^5 the following circuit is completed: battery Z⁸, wire c^{20} , armature c^{19} , contact c^{18} , wire c^{15} , relay X, wires c^{14} , x' , armature y , contact x^2 , wire x^3 , armature x^4 , contact x^5 , wires x^6 , c^{11} , contact c^{12} , armature c^{13} , ground z^7 . Consequently current is retained in the relay X during the vibration of the armature c^{10} in the motor magnet circuit causing current to be transmitted over the latter with each vibration of said armature, the motor magnet circuit then being completed over the following path: battery Z⁷, armature c^7 , contact c^6 , wire c^5 , magnet 27^c, wire c^8 , contact c^9 , armature c^{10} , wire c^{11} , contact c^{12} , armature c^{13} , ground z^7 .

The complete circuit of the line and mate relays can be traced as follows: (Fig. 6) battery Z, line relay coil 41^A, wires 40^A, 4^A, (Fig. 5) brush F', wire A², instrument A, wire A', brush F², wires 5^A, 50^A, (Fig. 6) mate relay coil 51^A, battery Z. If the operator at subscriber's station A now despatches the desired number of impulses over the circuit just delineated, the connector switch will be actuated to cause its wipers C' and C² to advance one or more steps into engagement with the terminals of the outgoing line circuit on which he desires to call a certain party. These impulses are caused by opening and closing said circuit the requisite number of times with sufficient rapidity or frequency, to release the armature c^{10} and to continue its vibration to successively close and open the circuit of the motor magnet 27^c, while the relays X and Y are retained in energized condition. To illustrate this operation succinctly, let it be considered that the called subscriber's station, heretofore referred to as B, is the instrument circuit connected to the set of contacts designated by the numeral 400 in Fig. 14, which is the fortieth set of contacts in the bank of contacts of the connector switch, necessitating forty steps of the movable contact elements or brushes (C', C², c^{17}) before

the latter can engage them. The impulse transmitter A⁴ will therefore be operated to open and close the contacts A⁴¹ and A⁴² forty times. Each impulse of current over the incoming line and mate wires (A', A², 4^A, 5^A, 40^A and 50^A) will energize both the line and mate relay coils 41^A, 51^A. The motor magnet circuit being closed by the slow relays C³, X, consequently receives a series of impulses in unison with those transmitted over the incoming instrument circuit, as it is successively opened and closed at the calling subscriber's instrument. Upon the cessation of these impulses the incoming calling line is closed and the armatures c^4 , x^4 and c^{10} are held in attracted position opening the circuit of the relay X, allowing the armature c^7 to drop back and destroy the circuits of the motor magnet and the relay Y. Both the starting and holding circuits of the relay X are now opened, the former being destroyed by the advancement of the switch and the latter by the dropping back of armature y . Now as the motor magnet circuit can only be energized when the armature c^7 is attracted, it is impossible to disturb the connector switch after it has been arrested. At this time the brushes of the connector switch rest in engagement with the terminals B¹¹ and B²¹ of the outgoing called circuit of instrument B.

Rendering a called line engaged.—Each set of terminals on the connector switch comprises a third terminal corresponding with and bonded to the terminal on the connector switch devoted to the circuit of the cut-off relay associated with each instrument circuit. This third terminal of the circuit of instrument B is indicated by c^{51} (Fig. 6), which is shown as connected to the cut-off relay B⁶ (Fig. 5) by the wire B¹⁶. Coöperating with this contact is the wiper c^{17} from which leads the wire c^{24} , terminating in the armature y' , on the relay Y, and coöperating with a back contact c^{25} connected by the wire c^{26} to a back contact c^{27} of an armature c^{28} connected to a ground z^9 over which current impulses are received from the battery Z⁹, connected with the coil of the cut-off relay B⁶ and supplying current to the following circuit: (Fig. 5) battery Z⁹, relay B⁶, wire B¹⁰, (Fig. 6) contact c^{51} , wiper c^{17} , wire c^{24} , armature y' , contact c^{25} , wire c^{26} , contact c^{27} , armature c^{28} , ground z^9 . The foregoing circuit energizes the cut-off relay of the outgoing called line to prevent the called subscriber from disturbing the finder switch, of any group of switches, when he answers the call and closes his line at the hook contacts B³.

The complete talking circuit from instrument A, the calling line, to instrument B, the called line, may now be traced as follows: (Fig. 5): instrument A, wire A²,

brush F', wires 4, 4^A, (Fig. 6) condenser 47, brush C', contact B²¹, wire B², (Fig. 5) instrument B, (Fig. 6) wire B', contact B'', brush C², wire 5^A, condenser 48, wires 5^A, 5, (Fig. 5) wiper F², wire A', instrument A. The current for talking purposes is supplied to the aforescribed circuit from the main battery Z over the wires 40^A, 50^A.

Delineated on Figs. 5 and 6 are the bond wires connecting the corresponding terminals of the lines of instruments A, B and J, which arrangement allows a call to be initiated on any line and permits one to be received from any other line. These bonds of instrument circuit A leading to the switch C are designated as follows: A¹⁰⁰, leading from the wire A' to the contact A¹⁰¹, A²⁰⁰ leading from the wire A² to the contact A²⁰¹ and the wire A¹⁵⁰ leading from the wire A¹⁵ to the contact A¹⁶¹.

In order to prevent the operation of the cut-off relays of those lines whose terminals are traversed by the brush c¹⁷ of the connector switch, the circuit of said brush is opened during its rotary movement by the attraction of the armature y'.

Restoring the switches to normal.—In order to return the connector switch to its normal position and to permit a similar movement of the finder switch, the release magnets 36^F and 36^C are arranged in a compound circuit which is opened when the line and mate conductors of an incoming or calling line are energized. This is accomplished by means of a switching relay S (Fig. 6) supplied with current from the battery Z¹⁰ over the wire s in the circuit comprising the wire s' connected to a back contact s² (Fig. 5) with which the armature f¹⁰ normally engages. The relay S is energized the moment the finder switch picks up an incoming calling line, by current transmitted over the following circuits: (Fig. 6) battery Z¹⁰, wire s, relay S, wire s', (Fig. 5) contact s², armature f¹⁰, wire f¹¹, brush f¹⁸, contact f¹⁶, wire A¹⁶, contact a¹⁵, armature a⁵, to ground z⁴. There is also a secondary circuit for energizing the switching relay S which causes it to pull up its armature in the event the finder switch is adjusted manually, comprising an armature s³ on the relay F³, connected by the tap s⁴ to the wire f¹¹, normally coöperating with the back contact s⁵ on the booster wire f.

The armature f¹⁴ on the release magnet 36^C (Fig. 6) has been heretofore referred to as forming part of the circuit of the release magnet 36^F, of the finder switch, to which it is connected by the wire f¹³. This armature when attracted is adapted to engage the forward contact c²⁹ connected by the wire c³⁰ to a back contact c³¹ of the armature c¹³ on the relay C³. One end of the coil of the release magnet 36^C of the switch C is connected by the wire c³³ to an

armature f³³ on the relay F⁶ of switch F, which normally engages a back contact f³⁴ to which the wire f⁷ is extended. The other end of the coil of said magnet 36^C is connected by the wire c³⁴ to an armature 70 c³⁵ on the relay C³, which normally engages a back contact c³⁶ connected by the wire c³⁷ to an armature c³⁸ on the switching relay S. This armature normally engages a back contact c³⁹ connected by the wire c⁴⁰ to the back contact c⁴² of the spring controlled switch arm c⁴¹. The armature c³⁸ when in attracted position engages the forward contact c⁴⁶ grounded at z³⁰. When both the switches are in normal position, the circuit 80 of the release magnet 36^F is open at the armature f¹⁴ and closed at armature c¹³, and the circuit of the release magnet 36^C is closed at the armatures c³⁵, c³⁸ and f³³, but is opened at the switch controlled spring arm c⁴¹. If 85 the wipers of the finder switch F are adjusted out of their normal position manually the spring f²¹ engages the contact f⁴² energizing the switching relay S over the following circuit: (Fig. 6) battery Z¹⁰, wire s, relay S, wire s', contact s², armature f¹⁰, wires f¹¹, s⁴, armature s³, contact s⁵, wire f¹⁰⁰, switch spring arm f⁴¹, contact f⁴², ground z¹⁵. The armature c³⁸ then attracted by relay S closes the following circuit: (Fig. 5) battery Z⁵, wire f⁷, contact f³⁴, armature f³³, wire c³³, (Fig. 6) magnet 36^C, wire c³⁴, armature c³⁵, contact c³⁶, wire c³⁷, armature c³⁸, contact c⁴⁶, ground z⁵⁰. The closing of the circuit of the magnet 36^C 90 insures the parts of the switch C being in a normal position and as it attracts the armature f¹⁴ the following circuit is then also closed: (Fig. 5) battery Z⁴, wire f¹², magnet 36^F, wire f¹³, (Fig. 6) armature f¹⁴, contact c²⁹, wire c³⁰, contact c³¹, armature c¹³, ground z⁷. An impulse of current over the foregoing circuit will return the movable parts of the finder switch F, but should the single impulse be insufficient to accomplish this result, successive impulses will be despatched over both of the described circuits through the medium of the armatures f²², f²³ and f³³. The detail view Fig. 12 is devoted to the release circuits of the finder and connector switches. The energizing of the release magnet 36^F attracted the armature f²² completing the following circuit: battery Z⁵, wires f⁷ and f¹⁰, relay F⁶, wire f²⁰, contact f²¹, armature f²², wire f²³, to ground z⁵, whereupon the armature f²³ and f³³ were attracted, the latter breaking the circuit of the magnet 36^C permitting said magnet to release the armature f¹⁴. The 95 momentary attraction of the armature f²³ completed the circuit of the line opening relay F³ as follows: battery Z⁵, wire f²⁴, relay F³, wire f²⁵, contact f²⁷, armature f²⁹, ground z⁵. Thus the armature s³ is caused 100 to disengage the contact s⁵ to destroy the circuit. 105

cuit of the switching relay S to enable the armature c^{38} to drop back into engagement with the contact c^{39} . When the switch C happens to be the one whose parts are operated manually, the circuit of the release magnet 36^c is closed over the following path: battery Z^5 , wire f^7 , contact f^{34} , armature f^{33} , wire c^{38} , magnet 36^c , wire c^{34} , armature c^{35} , contact c^{36} , wire c^{37} , armature c^{38} , contact c^{39} , wire c^{40} , contact c^{42} , switch spring arm c^{41} , ground z^8 . The closing of the circuit of the magnet 36^c also caused the circuit of the release magnet of the associate finder switch F to be energized by the attraction of the armature f^{14} , whereupon the relay F⁶ is caused to transmit an additional impulse of current over the circuit of the release magnet 36^c by vibrating the armature f^{33} until the arm c^{41} is disengaged from the contact c^{42} .

Opening the line.—In exchanges serving a large number of telephone instrument circuits, the associated finder and connector switches, shown in Figs. 5 and 6, are duplicated as many times as need be, providing pluralities of groups, such as those indicated by I, II and III, in Fig. 4, and on each switch in each group appear the terminals of the line and mate conductors. With such an arrangement or grouping of switches it will be seen that where two instrument circuits are connected over one set of switches, the movable contact elements of another group of switches, in traversing their respective banks of contacts, to effect a second connection, may pass over other unoccupied terminals of two instrument circuits previously connected. Therefore, if said wipers are supplied with current during their forward and retrograde movements a disagreeable click will be heard in the receivers of said connected telephone instruments. It has been previously intimated that in order to remove these objectionable noises provision is made for opening the line between the finder and connector switches during the time the finder switch is advancing to pick up an incoming line and also for the moment of time when both switches are released and are returning to normal position. This is accomplished in the present instance by means of the relay F³ controlling two armatures arranged respectively in the line and mate conductors, the former being indicated by 4^a, coöperating with a back contact 4^b, and the latter by 5^a, coöperating with a back contact 5^b. The relay F³ has been described as being one of the so-called slow or retarded relays and the two circuits by means of which current is supplied to it during the operation of the motor magnet 27^F and the operation of the release magnets 36^F and 36^c have been delineated heretofore. It will, therefore, be understood that this relay opens the ties

between the switches whenever the wipers of the finder switch are operated in one direction or the other.

Ringing and answering circuit.—The description thus far has been confined to the operation of the various elements which occur in the setting up of the connections between two telephone lines and to the mechanism operating conjointly therewith, by means of which a connection is automatically broken and the switches restored to their normal position. There still remains for further consideration additional mechanism by means of which the signaling devices on the outgoing or called lines are operated after the connection has been established, which are illustrated particularly in Fig. 10.

Each telephone instrument is provided with signaling devices such as the usual ringer (indicated by B⁷ at station B, Fig. 5), which are energized by signaling current from the generator K (Figs. 7 and 10) supplied to the outgoing line circuit, such as the wires B' and B². The signaling circuit is normally disconnected from the lines but by means of a ringing relay it is closed as soon as the connector switch has picked up the selected outgoing circuit, and is retained closed until the called subscriber answers. In order to supply this current intermittently to ring the bells or operate the signaling devices periodically, as well as to afford the answering subscriber an opportunity to cut his instrument onto the line, two additional elements are employed in conjunction with the generator K, namely, a signaling switch and a cut-through relay which is temporarily energized first, by said switch, and secondly, by the called subscriber closing his line.

Signaling switch.—The signaling switch R is similar to the one illustrated in Fig. 14, the essential difference therein residing in the arrangement of the terminals in its bank of contacts which is shown diagrammatically in Figs. 7 and 10. These terminals are arranged in three rows, said rows corresponding to the parts 12, 13 and 15, shown in Fig. 15, with which coöperate the movable contact elements or brushes R', R² and R³ respectively. The contacts of the first row of terminals are joined together in sets as indicated by r, r' of which there may be two or more, all joined to a conductor r² attached to the brush k of the generator K. These sets of contacts alternate with a plurality of blanks, such as r³, one of which is connected to a ground, as indicated by r⁴, for purposes that will presently appear. The majority of the terminals of the second row are also blanks, but each of those next succeeding the ones which are in alignment with the grounded terminals r³, of the first row, as indicated by r⁵, are joined to a con-

ductor r^6 which leads to an armature r^7 on the ringing relay R^7 . All of the contacts of the third row of terminals r^8 are tied together by a conductor r^9 , with the exception 5 of the last one r^{10} , which is dedicated to the function of effecting the release of the signaling switch.

A special starting and operating circuit for controlling the motor magnet 27^R of 10 the ringing switch and the release magnet 36^R thereof are employed which are controlled by the switching relay S , and another relay M not heretofore spoken of, called the assistant line answering relay. 15 Both of the last mentioned relays are shown in Fig. 8. On the switching relay S is an armature r^{11} (Fig. 8) which is connected by the wire r^{12} to an armature r^{13} , on the motor magnet relay R^5 . This armature 20 normally engages a back contact r^{14} , joined by the wire r^{15} to back contact r^{16} , of the armature r^{17} connected by the wire r^{18} to one end of the coil of the motor magnet 27^R . The other end of the coil of said magnet is 25 joined to the wire r^9 . The brushes R^2 and R^3 are both joined by the wire r^{19} to the battery Z^{11} . Referring again to the armature r^{11} on the switching relay S , it will be seen that when this is attracted it engages 30 a forward contact r^{20} joined by the wire r^{21} to the back contact r^{23} , of an armature r^{24} on the assistant line answering relay M , said armature having a ground z^{11} . Inasmuch 35 as the assistant line answering relay is not energized until the called subscriber answers in, the armature r^{24} normally engages the contact r^{23} , therefore it will be seen that each time the switching relay S is energized the following circuit is established: (Fig. 40) 7) battery Z^{11} , wire r^{19} , wiper R^3 , wire r^9 , magnet 27^R , wire r^{18} , armature r^{17} , contact r^{16} , wire r^{15} , contact r^{14} , armature r^{13} , wire r^{12} (Fig. 8) armature r^{11} , contact r^{20} , wire r^{21} , contact r^{23} , armature r^{24} , ground z^{11} . 45 This circuit causes the starting impulse to be given to the motor magnet 27^R to attract the armature r^{25} thereon into engagement with the forward contact r^{26} which is connected by the wire r^{27} to the motor magnet 50 relay R^5 . As the latter is connected with the battery Z^{12} , by the wire r^{28} , it also receives an impulse of current to open the starting circuit by the attraction of the armature r^{13} . The last mentioned relay R^5 55 is also one of the so-called slow or retarded relays, and is adjusted to discharge its residual magnetism slowly relatively to its motor magnet 27^R to cause the movable contacts, or elements, of the signaling switch to traverse its bank of contacts at a predetermined speed. Therefore, successive impulses of current will be transmitted to said motor magnet as long as the armature r^{11} 60 is held in attracted position, and the armature r^{24} is in its normal position. Likewise, 65

this switch is automatically released when the brush R^3 engages the last contact r^{10} , as this is joined by the wire r^{29} to the end of the coil of the release magnet 36^R , the other end of the said magnet being connected by 70 the wire r^{30} to the contact r^{31} of an armature r^{32} tapped onto the wire r^{12} . The release magnet relay indicated by R^6 is connected by the wire r^{33} to the battery Z^{12} and by the wire r^{34} to an armature r^{35} , coöperating 75 with the forward contact r^{36} also joined to the wire r^{12} . The energizing of the release magnet 36^R closes this circuit: (Fig. 7) battery Z^{12} , wire r^{33} , relay R^6 , wire r^{34} , armature r^{35} , contact r^{36} , wire r^{12} , (Fig. 8) armature r^{11} , 80 contact r^{20} , wire r^{21} , contact r^{23} , armature r^{24} , ground z^{11} . The relay R^6 is also a slow relay and the alternate opening and closing of the armatures r^{32} and r^{35} will cause one or more impulses of current to be transmitted 85 over the circuit of the release magnet 36^R , during which time the circuit of the motor magnet 27^R is broken by the attraction of the armature r^{17} .

Interposed in the line and mate conductors 4^A and 5^A at a point beyond the condensers 47 and 48 , are armatures 4^C and 5^C working on the cut through relay T which, in their normal positions, engage back contacts 4^e and 5^e , which are joined respectively 90 by conductors K' , K^2 with back contacts k' and k^2 coöperating with armatures k^3 and k^4 on the ringing relay, said armatures being likewise connected by conductors K^3 and K^4 with the brush R' , of the switch R , 95 and the brush k^5 of the generator K . The ringing relay R^7 which controls the armatures r^7 , k^3 , k^4 , is energized when the circuit of the motor magnet of the connector switch is broken by the dropping back of the armature c^7 , on the relay X , into engagement 100 with the back contact r^{37} . The circuit of this relay is also controlled by an armature r^{38} , on the switching relay S , by the armature c^{13} on the assistant line relay C^3 , and by an armature r^{39} on the busy relay V , said last mentioned armature being connected by the wire r^{40} to the contact c^{12} and normally coöperating with a back contact r^{41} , connected by the wire r^{42} with the forward contact r^{43} , of the armature r^{38} . The latter is connected by the wire r^{44} with one end of the coil of the ringing relay R^7 , the other end of said coil being connected by the wire r^{45} 110 with the back contact r^{37} . 115

From the foregoing description, taken in connection with Figs. 9 and 10, it will be observed that upon arresting the motor magnet 27^C and the resultant deenergization of the relay X the following circuit is closed: (Fig. 10) battery Z^7 , armature c^7 , contact r^{37} , wire r^{45} , ringing relay R^7 , wire r^{44} , armature r^{38} , contact r^{43} , wire r^{42} , contact r^{41} , armature r^{39} , wires r^{40} , c^{22} , c^{11} , contact c^{12} , armature c^{13} , ground z^7 . This causes the at- 120 125 130

traction of the armatures r^7 , k^3 , and k^4 closing the signaling circuit and the circuit of the cut through relay T. The ringing circuit may be traced over the following path: generator K, brush k, wire r^2 , contact set r, wiper R', wire K³, armature k^3 , contact k' , wire K', contact 4^c, armature 4^c, line conductor 4^A, wiper C', contact B²¹, conductor B², instrument B, ringer B', wire B', contact B¹¹, wiper C², mate conductor 5^A, armature 5^c, contact 5^c, wire K², contact k^2 , armature k^4 , wire K⁴, brush k^5 , generator K. Signaling current will traverse the foregoing circuit to operate the signaling devices of the selected outgoing instrument circuit during the time the brush R' of the ringing switch engages the set of contacts r. This circuit will then be broken until the brush has progressed into engagement with another set of contacts, such as r' , when the signaling devices will be again operated. During the time the brush R' is traveling from one set of contacts to the next, the brush R² wipes over contacts r^5 to give an impulse of current to the cut through relay T to cause the armatures 4^c and 5^c to be attracted into engagement with forward contacts 4^d and 5^d, to afford the called subscriber an opportunity to place his instrument circuit in connection with the circuit of the calling party. This cut through relay is indicated by T and is included in the following circuit: wire t, leading from the ground z^{111} adapted to receive current impulses from the battery Z¹¹, the wire, t' connected to an armature t^2 , on the assistant line answering relay M and co-operating with a contact t^3 joined by the wire t^4 to a forward contact t^5 co-operating with the armature r^7 , on the ringing relay R⁷, said armature being connected by the wire r^6 to the terminals r^5 which completes the circuit from the battery Z¹¹ when the brush R² engages said terminals. In the event the called party does not answer before the ringing switch R has completed its movement in one direction, the latter is automatically released when the brush R³ engages the last contact r^{10} , in the third row of terminals, as before explained, and continues to operate its wipers to intermittently signal the called subscriber until he answers, or until the calling party relinquishes his connection. This action on the part of the calling party restores the finder switch to its normal position, releasing the switching relay S and the assistant line relay C³ thereby opening the circuit of the ringing relay R⁷, which opens the circuit of the cut through relay T.

Answering in.—In order to close the gap in the line and mate conductors and to hold the armatures 4^c and 5^c in the attracted position when the called subscriber answers, an answering relay L is bridged across the line and mate conductors 4^A and 5^A between the condensers 47 and 48 and the contacts 4^d and

5^d which cuts back current for talking purposes, to the called party's line. This relay is similar to the line and mate relay and comprises tandem coils 41^B and 51^B, one end of each of which is connected, respectively, 70 with the line and mate conductors 4^A and 5^A by wires 40^B and 50^B, the other ends of said coils being connected to opposite sides of a battery Z¹³. The assistant line answering relay heretofore mentioned is indicated by 75 M and co-operates with the line answering relay L for accomplishing two purposes, namely, to open the starting circuit of the signaling switch R and to supply current continuously to the cut through relay T. 80 The relay M is adapted to be energized and retained in energized condition, when the line answering relay L is energized, by current from the battery Z¹⁴ which is connected to one end of the coil thereof, the other extremity of the latter being joined by the wire m to the armature m^2 which is attracted by relay L into engagement with the forward contact m^3 connected by the wire m^4 to a ground m^5 . A wire t^8 leads from the battery Z¹⁴ to a forward contact t^9 into engagement with which the armature t^2 may be attracted by relay M to complete the following circuit: battery Z¹⁴, wire t^8 , contact t^9 , armature t^2 , wire t' , relay T, wire t, to ground z^{111} . 90 Now, as the line answering relay L is retained in energized condition during the time the called party's line is closed at the receiver hook contacts, as B³, current is supplied continuously from the battery Z¹⁴ to 100 the cut through relay T and the armatures 4^c and 5^c are held in engagement with their forward contacts 4^d and 5^d, and as the armature r^{24} is also held in attracted position the starting circuit of the signaling switch R is 105 destroyed and advancing movement of the latter is stopped.

The complete talking circuit from instrument A, the calling subscriber's station, to instrument B, the called subscriber's station, may 110 now be traced as follows: (Fig. 5) instrument A, wire A', contact A¹⁰, wiper F², wire 5, contact 5^b, armature 5^a, wire 5^A, (Fig. 6) condenser 48, contact 5^d, armature 5^c, wire 5^A, brush C², contact B², wire B', (Fig. 5) 115 instrument B, wire B², (Fig. 6) contact B²¹, brush C', wire 4^A, armature 4^c, contact 4^d, condenser 47, wire 4^A, (Fig. 5) armature 4^A, contact 4^b, wire 4, brush F', contact A²⁰, wire A², instrument A. The current for 120 talking purposes is supplied at both ends of the above described circuit by the batteries Z and Z¹³, which will be understood is one and the same battery and common to all of those distributed throughout the illustrations.

Draining the line.—In the central energy telephone systems in which the signaling devices are bridged across the line, or instrument circuits, it is considered to be good 130

practice to interpose in such bridge a condenser, such as indicated by B^{70} in Fig. 5, through which the signaling current is transmitted. It happens occasionally, that this condenser retains a charge of residual current after the operation of the ringers has ceased, which may be sufficient to energize, for an instant of time, the tandem coils 41^B and 51^B of the line answering relay L when the cut through relay T pulls up, before the called subscriber answers, such an action giving what is called a false busy. This action may not occur every time a line is selected, but results if the condenser in the ringing circuit at the subscriber's instrument does not discharge completely at what is called the peak of the curve. To prevent this action one side of the ringing circuit is connected to the earth, as indicated at k^6 , which completes a path leading around the generator K when the brush R' of the ringing circuit engages one of the contacts r^3 grounded as indicated at r^4 . The complete ringing circuit has been described in connection with Fig. 10 and by reference to this figure it will be seen that the brush R' engages the contact r^3 when both the conductors K^4 and K^3 are connected to the called instrument circuit, on which the ringing current was previously despatched, so that a circuit is then completed around the generator K, as follows: wire K^4 , ground k^6 , ground r^4 , contact r^3 , wiper R', wire K^3 , whereby, the moment this circuit is completed, any residual current or charge remaining in the condenser B^{70} of instrument B will be drained off the line. By positioning the grounded contact r^3 in front of the contacts r^5 this draining of the line takes place before the wiper R^2 co-operates with the latter to energize the cut through relay T.

Busy test.—It has been shown in connection with Figs. 5 and 6 how two instrument circuits when connected through a pair of associate finder and connector switches are rendered engaged or busy by the energizing of their respective cut-off relays, which is sufficient where only one group or pair of finder and connector switches is employed, but where additional groups of such switches are used, as indicated in Figs. 3 and 4, it is possible that when the circuits of two instruments, such as A and B, are connected a third subscriber may endeavor to establish a connection between the circuit of his instrument and one of those already in use over another group of switches, for instance, the subscriber of instrument J might endeavor to effect a connection over group III with the circuit of one of the instruments A or B previously connected over the switches included in group I, or with the circuits of instruments H and G, connected over the switches of group II. In order to prevent

the interference and annoyance which would result with a possibility of interconnection or intercommunication of more than two instrument circuits and to inform the third party who may unknowingly attempt to connect his instrument circuit with the circuit of some other instrument in use at that time, there is combined with the apparatus heretofore described means for despatching, over the calling party's line, a busy signal when the wipers of the connector switch of the group of switches over which the third party has initiated a call passes into engagement with the coördinate terminals of the trunk of these terminals similarly engaged by the wipers of a connector switch of some other group. The devices affecting the busy signal comprise a busy relay V, which operates in conjunction with the relays X and Y, and the line answering relay L, all of which operate conjointly to close a circuit connected with the incoming instrument circuit on which a call has been initiated. This busy signal apparatus is shown particularly in Fig. 11 which may be combined with Figs. 6 and 7 by placing this illustration between the latter. The calling circuit over which the tone or returning busy signal is despatched may be traced completely on Figs. 7 and 8. The tone or returning busy signal is also produced by the generator K in combination with the signaling switch mechanism R and means for producing an induced current comprising a primary coil P and a secondary coil P' connected in series with a condenser P² between them, one end of each of said coils being grounded as indicated at P³. The other extremity of the primary coil P is connected by a wire p (Figs. 11 and 7) to a forward contact p' of an armature p² connected by a wire p³ with the ringing circuit conductor K³. The corresponding end of the secondary coil P' is connected by the wire p⁴ with an armature p⁵, on the busy relay V which is attracted by the latter, at certain times, into engagement with a forward contact p⁶ on the wire p⁷, joined to the wire 50^B, connected to the line wire 5^A in proximity to the condenser 48. It will be remembered that the signaling switch R is in continuous operation whenever two instrument circuits are connected and that its wipers traverse its bank of contacts successively until the switch is arrested. Therefore, as this signaling switch is common to the several groups of connector and finder switches, it performs its function whenever a connection is established on any group of switches. It will be further seen that whenever the signaling switch is in operation that the armature p² is attracted by its motor magnet relay R⁵ and that a circuit through the primary coil P is established over the following path: generator K, brush k, wire r², contacts r (or r') wiper

R', wire p^3 , armature p^2 , contact p' , wire p , coil P and the common grounds P^8 and k^6 .

During the operation of the connector switch C the line and mate tandem coils 5 41^a and 51^a and the local assistant line relay C³ remain energized and while the motor magnet 27^c is operating, and the two relays X and Y are also energized. In this 10 connection it has been explained, by reference to the motor magnet circuit shown in Fig. 9, the manner in which the relays X and Y successively release their respective armatures. This principle of allowing the current to discharge from one of these 15 relays to deenergize it before the other relay is rendered inactive, performs an important function in connection with the busy test, permitting the busy relay V to be supplied with current in the event the selected instrument circuit has been rendered engaged 20 by a previous connection established over another group of switches. This circuit constitutes a starting circuit which energizes the busy relay V to close its own holding circuit. The energizing of the busy relay, in 25 addition to cutting the tone circuit into the circuit of the calling subscriber's line, cuts off the ringing circuit from the outgoing or called subscriber's circuit and prevents 30 the latter from being cut through by the relay T, for the purpose of preventing the busy tone signal from being applied to the circuit of the called party, over the terminals of the trunk connection, or branch, 35 leading from said called party's instrument circuit to the connector switch of that group of switches over which the third calling party attempts to make a connection.

On the relay X is a second armature x^7 40 (Fig. 11) coöperating, when in its normal position, with a back contact x^8 , joined by the wire x^9 to a forward contact y^2 of the armature y' . Leading from the armature x^7 is a wire v which terminates in a forward contact v' of the armature r^{39} on the 45 busy relay V. Extending from the wire v is a branch v^4 terminating in a back contact v^5 of an armature v^6 on the line answering relay L. Connected to this armature is 50 a wire v^7 leading to one of the terminals of the coil of the busy relay V, the other extremity of which is connected by the wire v^8 to a battery Z^{15} . Leading from the wire v^4 is an extension v^9 terminating in a 55 forward contact v^{10} of the armature r^{24} on the assistant line answering relay M.

Starting with the premise that the instruments A and B are connected by the 60 switches of group I and the subscriber of instrument J endeavors to obtain a connection with the circuit of instrument B over the switches of group III, it will be seen that the following action takes place the moment the wipers of the connector switch of group III engage the coördinate termi-

nals of instrument circuit B. The motor magnet of the connector switch of group III ceases its operation and the line and mate tandem coils thereof remain energized so that relay X is deprived of current by the 70 opening of its holding circuit (at armature x^4 , Fig. 9) permitting the armature x^7 to drop back into engagement with the contact x^8 . The relay Y, it will be remembered, is supplied with current only during the time 75 relay x is energized and holds the armature c^7 (Fig. 9) in engagement with the contact c^6 , consequently relay Y is not deenergized until after relay X has been deprived of current, armature y' (Fig. 11) 80 is held in engagement with the forward contact y^2 until relay Y lets go. When the brushes of the connector switch of group III picked up the set of contacts thereon belonging to the circuit of instrument B, the third 85 wiper c^{17} thereof engaged the terminal of the circuit of the cut-off relay B^c. Now, the circuit of the last mentioned relay was completed at the time the connector switch of group I came to a position of rest. The 90 cut-off circuit terminals on each switch are bonded together, or connected, by trunks, as will be understood, although these have been omitted to simplify the illustrations, however one of them has been shown on combined Figs. 6 and 11 as comprising the wire B¹⁶¹, said figures when joined illustrating the complete circuit of the busy relay V of the connector switch of group III which may be traced as follows: (Fig. 11) battery 95 Z¹⁵, wire v^8 , busy relay V, wire v^7 , armature v^6 , contact v^5 , wires v^4 , v , armature x^7 , contact x^8 , wire x^9 , contact y^2 , armature y' , wire c^{24} , wiper c^{17} , contact c^{51} , trunk B¹⁶¹, into 100 group I—(Fig. 6) contact c^{51} , wiper c^{17} , wire c^{24} , armature y' , contact c^{25} , wire c^{26} , contact c^{27} , armature c^{28} , ground z^9 . The impulse of current which traverses this circuit before the slow relay Y of group III released its armature y' , causes the armatures 105 p^5 and r^{39} to be attracted, the latter closing the following circuit: battery Z¹⁵, wire v^8 , busy relay V, wire v^7 , armature v^6 , contact v^5 , wires v^4 , v , contact v' , armature r^{39} , wires r^{40} , c^{22} , and c^{11} , contact c^{12} , armature 110 c^{13} , ground z^7 , thus completing the holding circuit of the busy relay of group III to retain it in energized condition until said circuit is broken by the deenergizing of the local assistant line relay C³ and the dropping back of its armature when the third calling party opens his instrument circuit.

By referring to Fig. 10, it will be seen that several different things are accomplished when the busy relay of a connector 115 switch mechanism is energized. First the circuit of the ringing relay R' is opened, by the attraction of the armature r^{39} . This relay then allows its armatures k^3 , k^4 and r^7 , to return to their normal position, the 120

two former opening the ringing circuit leading from the generator K and the signaling switch R, while the armature r^7 opens the circuit of the cut through relay T. This 5 relay then has no effect upon the armatures 4^c and 5^c with the consequent result that the line answering relay L cannot be energized, which would otherwise occur when the wipers C', C² of the connector switch of 10 group III picked up the coordinate terminals of the closed circuit of instrument B, to thus prevent the busy signal or tone from passing out over this group of switches onto the busy called instrument circuit. The at- 15 traction of the armature p^5 closed the circuit leading from the secondary coil P' which may be traced on the combined Figs. 11 and 7 as follows: (Fig. 11) ground P³, condenser P², coil P', wire p^4 , armature p^5 , 20 contact p^6 , wires p^7 , 50^B, condenser 48, mate wire 5^A, (Fig. 7) armature 5^a, contact 5^b, wire 5, brush F², (it being considered at this time that the finder switch F of group 25 III has picked up the terminals of the circuit of instrument J, the incoming calling circuit), wire J', instrument J, wire J², wiper F', wire 4, contact 4^b, armature 4^a, wire 4^A, (Fig. 11) condenser 47, wire 40^B, coil 41^B, to ground at m⁵. The impulses of 30 current induced in the last described circuit as the brush R' of the ringing switch traverses successively the sets of contacts r and r' causes an intermittent humming or buzzing sound or tone, which may be varied in 35 intensity to any desired degree, to be reproduced by vibrations of the diaphragm in the receiver 2 of the calling party, in the present instance the subscriber at station J.

Effecting a disconnection by either of two connected parties.—It has been explained in 40 connection with Figs. 5 and 6 the manner of restoring the finder and connector switches to their normal position automatically by the opening of the circuit of the instrument from which a call was initiated. These release operations take place on each 45 group of switches in the same manner, but when a plurality of the latter are employed, in conjunction with the busy test devices 50 just described, the called party may at his option disconnect his line or instrument circuit from a connection through one group of switches and establish a different connection over another group of switches, in 55 which event the busy test on the first group of switches will be "kicked up," or put into operation, to inform the other party that his line of communication has been severed. The closing or answering in of a called 60 instrument circuit selected by a connector switch, it will be recollected, energized the line answering relay L with the assistant line answering relay M and the cut through relay T. The first mentioned relay L opened 65 the circuit of the busy relay V, by attract-

ing the armature v^6 , and the second mentioned relay M attracted the armature r^{24} into engagement with the contact v^{10} . As current is held in the relay M by the energizing of the relay L it follows that the former cannot be deenergized until after the circuit of the latter has been destroyed. Therefore, when a called party opens his instrument circuit the armature v^6 drops back into engagement with the contact v^5 and an 70 impulse of current is transmitted to the busy relay V, before the deenergizing of the relay M takes place, the following circuit at that time being momentarily established: battery Z¹⁵, wire v^8 , relay V, wire v^7 , armature v^6 , contact v^5 , wires v^4 , v^9 , contact v^{10} , 75 armature r^{24} , ground z^{11} . The busy relay V then receives current over the aforescribed holding circuit and a busy signal or tone is returned to the previously connected calling 80 subscriber, which continues until he causes the connector and finder switches to be restored to their normal position by opening his instrument circuit. It is to be remembered that the closing of the called party's 85 line caused the armature r^{24} , to be held in attracted position, thereby destroying the circuit of the ringing switch, r , and vice versa, the opening of the called party's line at the receiver hook will cause the armature, 90 r^{24} , to assume its normal position, thereby again closing the starting circuit of said 95 ringing switch, r .

The distributor mechanism. The operating mechanism of the finder switches has 100 been described as operating automatically when actuated in the first instance by the closing of an instrument circuit, but in order to distribute a plurality of calls successively over different groups of switches, it is necessary to interpose between the instruments and said groups mechanism which is itself actuated by the closing of an instrument circuit and in turn actuates the finder switch of one or more groups. This mechanism is 105 illustrated particularly in Fig. 7 and comprises switching mechanism D which is operated in a manner similar to the finder switch F, although it comprises but two rows of terminals in its bank of contacts, one of 110 which is devoted to the terminals of the starting circuits or booster lines of the finder switches of the several groups of switches. In fact, the distributor mechanism is interposed in said circuits and is merely a means of extending them to one or another of said 115 finder switches, as it comprises a wiper D' in the circuit of the wire f coöperating with terminals from which lead the wires f', f^{II}, f^{III}, leading respectively to the groups of 120 switches, I, II and III, said terminals being located respectively at equidistant points on the bank of contacts, the intermediate contacts, indicated by d, being bonded together 125 and connected by a wire d' with a ground d². 130

The operating mechanism of the distributor switch comprises a motor magnet 27^D, a motor magnet relay D⁵, a release magnet 36^D, and a release magnet relay D⁶. The circuit 5 for the motor magnet comprises a wire d³ leading from the wire f to a back contact d⁴ of an armature d⁹ connected by the wire d⁶ to one end of the coil of said magnet 27^D, the other extremity of which is connected by 10 the wire d⁷ to a back contact d⁸ of an armature d⁹ connected by the wire d¹⁰ to a battery Z¹⁶. The relay D⁵ is connected to the last mentioned battery and is in the circuit of the wire d¹¹, connected to the forward contact d¹² of the armature d¹³ grounded at 15 z¹⁶. The armature d¹³ is arranged on the motor magnet 27^D and is attracted whenever the motor magnet circuit which is closed 20 when the actuating relay of one or another of the instrument circuits is energized, said circuit being traceable on Fig. 7, as follows: battery Z¹⁶, wire d¹⁰, armature d⁹, contact d⁸, wire d⁷, motor magnet 27^D, wire d⁶, armature d⁹, contact d⁴, wires d³, f, contact f⁶, 25 armature a⁵, ground z⁴. The attraction of the armature d¹³ energizes the relay D⁵ over the following circuit: battery Z¹⁶, relay D⁵, wire d¹¹, contact d¹², armature d¹³, ground z¹⁶, attracting the armature d⁹ to break the 30 motor magnet circuit, and as said armature continues to alternate with the armature d¹³ the movable contact elements or wipers of the switch D will be advanced progressively step by step until its motor magnet 35 circuit is opened. The wiper D' of the distributor switch in stepping around in search of a trunk leading to an idle group of switches, actuates the latter as soon as it engages the terminal of the booster line leading thereto. The booster switch then being 40 set into operation steps off to pick up the incoming or calling line and when engaging the terminals thereof it causes the circuit of the cut-off relay to be energized and thus 45 destroys the starting circuit of the distributor switch. The reason for causing the continuous operation of the distributor, until the cut-off relay of the calling line has been actuated, is to insure the starting of the 50 distributor switches of a second or third group to insure the picking up of a calling line, should the booster switch which was actuated first fail to accomplish this object.

The release of the distributor switch is 55 effected by the release magnet 36^D which is in the circuit commencing with the brush D², the wires d¹⁴, and d¹⁵, terminating in the contact d¹⁶ with which co-operates the armature d¹⁷ connected to the battery Z¹⁷. The 60 brush D² co-operates with the second row of contacts of the distributor switch which are all blanks, with the exception of the last one, indicated by d¹⁸, which is connected to the ground d², as shown, to complete the following circuit, when the wipers of said switch 65

have reached their limit of movement in a forward direction: battery Z¹⁷, armature d¹⁷, contact d¹⁶, wire d¹⁵, magnet 36^D, wire d¹⁴, brush D², contact d¹⁸, ground d². The release relay D⁶ is supplied with current 70 from the battery Z¹⁷ by a wire d¹⁹, the remainder of the circuit including the wire d²⁰, connected to the terminal d²¹ of the armature d²² connected to ground z¹⁷. The armature d²² and the armature d¹⁷ are 75 arranged respectively on the release magnet 36^D and its associate relay D⁶ and are both attracted to alternately close the circuit of the relay and open the circuit of the release magnet and as the circuit of the motor magnet is opened by the attraction of the armature d⁶, its interference with the return movement of the wipers is prevented. 80

When the entire mechanism of the exchange is in normal position the contact element or wiper D' of the distributor switch stands, in the position shown in Fig. 7, in engagement with the terminal of the booster line f¹. Consequently an impulse of current despatched from any instrument circuit over 85 the wire f will pass directly through the distributor mechanism to the booster switch F of group I and part of said current will be diverted into the circuit of the motor magnet 27^D to start the distributor switch. The starting of the latter steps the brush D' onto one of the grounded sets of contacts d which automatically causes the continued movement of said switch until the wiper D' steps onto a contact of a booster line of a 90 group of switches which is open, such as the contact of the line f^{II} in Fig. 7. Should it occur that this group of switches were busy, as shown in Fig. 4, the motor magnet of the distributor switch would receive another 95 impulse of current and continue operating until the wiper D' passed into engagement with the terminal of the booster line f^{III}, leading to group III, when it will stand in the position shown in Fig. 4 in readiness to 100 actuate the switches of group III upon the next incoming call. The circuit which energizes the motor magnet of the distributor switch to advance it beyond the terminals of the booster line of a busy group of 105 switches may be traced on Fig. 7, it being understood that the booster circuits of each group indicated by f^{II} and f^{III} are the same for each group of switches and that when the booster switch of a group has been advanced out of its normal position the spring switch contacts f⁴¹ thereof are in engagement with their respective forward contacts f⁴²; battery Z¹⁶, wire d¹⁰, armature d⁹, contact d⁸, wire d⁷, motor magnet 27^D, wire 110 d⁶, armature d⁹, contact d⁴, wire d³, brush D', wire f¹, (or f^{II}, f^{III}) wire f¹⁰⁰, spring switch arm f⁴¹, contact f⁴², ground z¹⁵. 115

Multiple switches.—The length of time required to set up a connection, or establish a 120

call, may be minimized by employing a multiple arrangement of finder switches, preferably arranged in pairs, the equivalent sets of terminals on each being located relatively 5 in reverse position in the banks of contacts on the two switches, which in practice gives the same result as would be obtained if the mechanism of one switch of a pair was designed to drive its contact elements in a 10 reverse direction relatively to the movement of the wipers of the other switch. The switch illustrated in Fig. 14 is provided with fifty sets of line circuit terminals, requiring fifty movements or steps of the wipers to 15 bring them into engagement with the last set of terminals and, although the switch mechanism travels with considerable alacrity, it will be seen that the time required to enable the switch wipers to move into 20 engagement with the last set of terminals, is twice as long as that consumed while the wipers are moving to the center of the bank of contacts to engage the twenty-fifth set of terminals. Consequently by tying each line 25 circuit to two switches and either arranging the terminals thereon in inverse order, or rotating the wipers of one of them in a relatively opposite direction to those of the other switch, the total number of lines may 30 be traversed in twenty-five steps thereby reducing the time to one-half of that required by a single switch for making the selection of a line having the highest number. To describe this idea more specifically, the circuit 35 of instrument B was stated to be connected to the fortieth set of contacts, designated by 400 in Fig. 14, requiring forty steps of the finder switch F. On a second finder switch (such as F¹⁰, Fig. 13), the circuit of instrument B would be joined to the tenth set of terminals, occupying the position designated by 100 in Fig. 14, so that the movable contact elements of this second switch would 40 only be required to move ten steps to select 45 said instrument circuit. In Fig. 13 this duplication of finder switches is illustrated diagrammatically to show the arrangement of terminals corresponding to the circuits of instruments A and J, of Figs. 5 and 6, and 50 3 and 4. The switches F and C are identical with those shown in said figures, and the operating mechanism of the other finder switch F¹⁰, is like that of the switch F, but 55 associated with it is a separate connector switch C¹⁰, which performs the same function as the corresponding switch C, when an instrument circuit is selected by the finder switch F¹⁰. It will be noticed that the sets 60 of terminal contacts A¹⁷ and J¹⁷ on the latter, are in reverse position in the switch bank, relatively to the corresponding sets A⁷ and J⁷ on the switch F, while the sets of connector switch terminals J⁸, J¹⁸ and A⁸, A¹⁸, 65 occupy the same relative position in the two connector switch banks. When this multi-

plication of the switches is employed, each group comprises a major set such as F and C and a minor set such as F¹⁰ and C¹⁰ illustrated in Fig. 13. Each of said sets is propelled by operating mechanism the same as 70 that illustrated completely in Figs. 7 and 8. For convenience in further description the minor sets of switches belonging to the several groups are indicated generically by reference characters I^a, II^a and III^a. In order 75 to actuate the finder switches F and F¹⁰ of the major and minor sets of each group simultaneously, or more accurately speaking, in quick succession, the minor booster line of the finder switch F¹⁰ terminates in a 80 contact adjacent the terminal of the booster line of the finder switch of the major set, as shown in the diagrammatic views (Figs. 4 and 13). These minor booster lines are indicated respectively by a^I, a^{II} and a^{III}. From 85 an inspection of Figs. 4, 7 and 13 it will be seen that whenever the distributor mechanism is started by the energizing of a booster circuit, at least two finder switches are 90 started in operation in quick succession to 95 find the terminals of the incoming line or calling instrument circuit. The switch, the movable elements of which first pick up the terminals of said calling line circuit will be arrested, as heretofore described, while the 100 finder switch of the other set in the same group continues its excursion. It will be recollected that the instant the finder switch is arrested the cut-off relay of the calling line is energized, permitting the operating- 105 holding circuit branch of said switch (which was previously opened) to be closed. The closing of this circuit branch occurs before the movable contact elements or wipers of the other finder switch (which is still advancing) engage the second set of terminals of the calling instrument circuit, which latter are connected by the trunking lines to 110 the set of contacts engaged by the arrested finder switch of the same group. Consequently, the advancing finder switch is not arrested at said set of terminals, but is permitted to operate until its wipers pass over the entire bank of contacts and disengage 115 the last set of terminals thereof, when it is automatically returned to its normal position. Referring particularly to Fig. 13, if the finder switch F¹⁰ happens to be the one which picks up the incoming calling circuit, then the latter is extended to the associate 120 connector switch C¹⁰ which is operated to select the desired outgoing called circuit, the other connector switch C remaining idle. In addition to facilitating the quick selection of an incoming calling circuit, as before mentioned, this duplication of the 125 finder switches possesses the advantage of making the selection of a circuit doubly assured, for should the movable contact elements of one switch happen to miss a con- 130

nection, due to corroded terminals, or a too rapid movement of the wipers, or some other unaccountable cause, then the other finder switch will pick it up.

- 5 There is another advantageous point gained by the controlling of the distributor mechanism by means of the actuating and cut-off relays associated with each instrument circuit, which is yet to be described.
- 10 It has been shown that the motor magnet circuit of the distributor switch is completed when an actuating relay is energized by the closing of a calling instrument circuit and that this motor magnet circuit is held closed 70
- 15 by said relay until the latter is robbed of current by the action of its associate cut-off relay, which is energized when the corresponding instrument circuit is picked up by a finder switch. Presumably this relay will 80
- 20 be energized by one of the finder switches, such as F or F¹⁰, of the major and minor sets of the group of switches set into operation upon the first impulse of current transmitted to the distributor switch. It will be no- 85
- 25 ticed, however, that in the diagrammatic illustrations showing the relative arrangement of the terminals of the primary and secondary booster lines, that these are located in pairs and that each pair is sepa- 90
- 30 rated from the others by equidistant spaces filled with contacts representing a plurality of steps which the wiper D' of the distributor switch must take as it passes from the terminals of one set of booster lines to those 95
- 35 of another set. These spacing contacts are all tied to ground or one side of the battery. This spacing of the booster line terminals is sufficient to allow the finder switches of a group to select a given in- 100
- 40 strument circuit and in practice the wipers of the finder switches travel at a greater speed than the brushes of the distributor switch. As before stated, the motor magnet circuit of the distributor switch remains 105
- 45 closed until it is opened by its associate cut-off relay, consequently if an incoming calling line circuit is not picked up by the sets of switches of a group which are first actuated the cut-off relay of said instrument 110
- 50 circuit fails to operate and a second or third group will be excited. In the event the cut-off relay of a calling instrument circuit pulls up to destroy the starting circuit of the distributor switch when the brush D' is be- 115
- 55 tween two pairs of booster line terminals, the motor magnet continues to receive current over the grounded intermediate contacts d but is arrested when the brush D' reaches the terminal of a booster line lead- 120
- 60 ing to an idle group of switches. This method of controlling the distributing switch mechanism permits one or another of the switches of a group or the entire group thereof to be removed without interference 125
- 65 with the operation of the switches of the

remaining groups. From an engineering standpoint this is an advantageous feature of construction because it enables the operator to remove a switch for purposes of repair and to facilitate locating the cause of 70 trouble arising from any source.

Lamp supervision.—In order to afford the chief operator or clerk in charge of the central office apparatus information regarding the operation of the various switches a system of pilot lights are employed in connection therewith, which may be located at any convenient point for observation preferably on the operator's desk. One of these lamps may be arranged in connection with each 75 switch, if desired, those on the finder switches being arranged in the circuit of the motor magnet relay F⁶ as indicated at F⁷ in Fig. 5. In practice it has been found sufficient for all practical purposes to employ 80 but one lamp located in the circuit of the motor magnet of each connector switch, as indicated by C⁷ in Figs. 6, 8 and 9, which is supplied with current from the battery Z⁸ whenever the primary controller or switch- 85

ing relay C³ is energized. A cross or permanent ground on a subscriber's instrument circuit closes the actuating relay and starts a finder switch. The latter causes the switching relay S of the associate connector switch to be energized. This relay opens the circuit of the release magnet of said connector switch. The closed instrument circuit also energized the line and mate relay coils and the local relay C³. This combination of effects causes the relays X and Y to be energized. However, as no impulses are transmitted over said instrument circuit to advance the connector switch the lamp continues to burn until the trouble is remedied, the circuit over which it receives current being traceable as follows: (Fig. 6) battery Z⁸, lamp C⁷, wire c²⁰, armature c¹⁹, contact c¹⁸, wire c¹⁵, relay X, wire c¹⁴, contact c¹³, spring arm c¹¹, ground z⁸. In its regular operation the connector switch is advanced out of its normal position almost immediately to destroy the above circuit.

From the foregoing it may be observed that if the lamp is not ignited, or after being ignited is not extinguished, it is an indication of trouble which may be traced directly to and located by aid of the set of switches belonging to this lamp.

I claim as my invention:

1. In an automatic telephone exchange system, the combination with a plurality of normally open instrument circuits and a finder switch mechanism comprising terminals for said circuits, contact elements co-operating therewith and electro-magnetic devices actuated when an instrument circuit is closed to cause the elements to traverse the terminals until engaging those devoted to the closed instrument circuit, of a con-

- nectar switch mechanism also comprising terminals for said instrument circuits, contact elements and a motor magnet for advancing them progressively having a normally open circuit, of ties between the contact elements of the finder and connector switches, devices on each instrument circuit for transmitting impulses of current thereover, a relay controlling the motor magnet circuit having coils bridged in each tie which are simultaneously energized and deenergized in unison with current impulses despatched over an instrument circuit and a source of current supply for said circuits.
- 15 2. In an automatic telephone exchange system, the combination with a plurality of instrument circuits, finder and connector switching mechanisms each comprising terminals for said lines, contact elements co-operating therewith and operating devices for advancing them progressively, said devices of the finder switch being automatically actuated to cause its elements to pick up the terminals of a calling instrument circuit and the corresponding devices of the connector switch being arranged to cause its wipers to be advanced progressively into engagement with the terminals of another circuit, of ties between the contact elements of the two switches, means for transmitting impulses of current over a calling instrument circuit, mechanism comprising a relay having tandem coils which are energized in unison with current impulses despatched over a calling instrument circuit which controls the operating devices of the connector switch and a source of current supply for said circuits.
- 30 3. In an automatic telephone exchange system, the combination with a plurality of instrument circuits, each comprising a line and a mate conductor, finder and connector switching mechanisms each comprising terminals for said circuits, contact elements co-operating therewith and separate operating devices for advancing them progressively, said devices of the finder switch being adapted to cause its elements to automatically advance into engagement with the terminals of a calling instrument circuit, the operating devices of the connector switch being arranged to advance its elements in unison with current impulses despatched over the calling instrument circuit after said circuit has been selected by the finder switch, means for transmitting impulses of current over a calling instrument circuit, of line and mate conductors forming ties between the contact elements of the two switches, mechanism for controlling the operating devices of the connector switch comprising a relay having tandem coils bridged into each of the ties which are energized in unison with current impulses transmitted over the line and mate conductors and a source of current supply for said circuits.
- 35 4. In a switching mechanism, the combination with a movable element, a set of contacts normally closed by the latter and devices for driving said element comprising a motor magnet having a circuit provided with two sets of normally open contacts and a set of normally closed contacts, an operating relay for controlling the latter, an assistant operating relay for closing one of the sets of contacts and a secondary relay for closing the other set of open contacts, a starting circuit for the secondary relay leading through the set of contacts controlled by the switch element and having an open set of contacts adapted to be closed by the assistant operating relay, a third relay which is energized when the secondary relay is operated, a holding circuit for the latter having an open set of contacts adapted to be closed by the third relay and a closed set of contacts adapted to be opened by the operating relay, of a circuit for the operating relay and means for transmitting impulses of current thereover, a circuit for the assistant operating relay and a source or current supply for said circuits.
- 40 5. In an automatic telephone exchange system, the combination with a normally open instrument circuit and means for closing it, and other means for transmitting current impulses thereover, a movable switching element and devices for driving it comprising a motor magnet having a circuit provided with two sets of normally open contacts and a set of normally closed contacts, a line relay located in the instrument circuit and controlling the closed set of contacts, an assistant line relay having a circuit energized by the line relay and controlling one of the sets of open contacts, a secondary relay controlling the other set of open contacts, a holding circuit for said secondary relay having an open set of contacts closed when the line relay is deenergized and another set of open contacts, a fourth relay for closing the latter which is rendered operative during the time the motor magnet circuit is energized and a source of current supply for said circuits.
- 45 6. In a telephone exchange system, the combination with a plurality of instrument circuits, finder and connector switching mechanisms comprising terminals of said circuits, movable elements co-operating therewith, means for advancing them and devices for restoring them embodying electromagnets, a circuit for the magnet of the finder switch adapted to be closed when the magnet of the connector switch is energized, and a normally open circuit for the last mentioned magnet, of a switching relay for closing said last mentioned circuit which is ren-

dered inoperative during the advance movement of the finder switch mechanism and a source of current supply for said circuits.

7. In a telephone exchange system, the combination with a plurality of normally open instrument circuits, finder and connector switching mechanisms each having terminals for said circuits and movable elements coöperating therewith, the finder switch comprising mechanism for automatically advancing its elements when an instrument circuit is closed and the connector switch embodying mechanism adapted to be actuated by current impulses transmitted over said closed instrument circuit, a line relay and a switching relay both of which are energized after the finder switch has picked up the terminals of the closed instrument circuit, of separate restoring devices for the two switches comprising electromagnets, a circuit for the magnet of the finder switch which is rendered active upon the energizing of the magnet of the connector switch, a circuit for the last mentioned magnet having normally closed and normally open sets of contacts arranged on the line and switching relays and a source of current supply for said circuits.

8. In an automatic telephone exchange system, the combination with a plurality of normally open metallic instrument circuits, a plurality of groups of associated finder and automatic connector switching mechanisms which are normally inoperative, said groups each serving to connect any instrument circuit with any other circuit, of a distributing mechanism which is actuated when instrument circuits are closed to successively render different groups of switches operative.

9. In an automatic telephone exchange system, the combination with a plurality of normally open instrument circuits, a plurality of groups of associated finder and connector switching mechanisms each having terminals for said circuits, movable elements coöperating therewith, the finder switches embodying motor magnets which automatically advance their elements to pick up closed calling instrument circuits, the connector switches embodying mechanism adapted to advance their elements to connect said circuit with another circuit, of a distributor switching mechanism comprising terminals, a contact element coöperating therewith and electromagnetic mechanism for advancing it, a booster line connected to said element, circuits for said motor magnets leading to the terminals, means for energizing said booster line when an instrument circuit is closed and deenergizing it when a finder switch has picked up the terminals of said circuits.

10. In an automatic telephone exchange system, the combination with a plurality of

normally open instrument circuits, a plurality of groups of associated finder and connector switching mechanism each having terminals for said circuits and movable elements coöperating therewith, the finder switches embodying motor magnets which automatically advance their elements to pick up closed calling instrument circuits, the connector switches embodying mechanism adapted to advance their elements to connect said circuit with another circuit, of a distributor switching mechanism comprising terminals, a contact element coöperating therewith and electromagnetic operating mechanism for advancing it comprising a motor magnet, starting circuits for the motor magnets of the finder switches leading to said terminals, a booster line supplying current to the distributor switch element and its motor magnet and means for energizing it when an instrument circuit is closed.

11. In an automatic telephone exchange system, the combination with a plurality of normally open instrument circuits, a plurality of finder switches each having terminals for said circuits and movable contact elements coöperating therewith, means for operating said elements embodying a motor magnet, said finder switches being associated in pairs, a distributing switch having terminals, a movable contact element coöperating therewith, mechanism for advancing it comprising a motor magnet, of starting circuits for the motor magnets of the finder switches leading to the terminals of the distributor switch, said circuits of each pair of finder switches being connected to adjacent terminals, a starting circuit for the motor magnet of the distributor switch, means for energizing it and successively energizing the corresponding circuits of one pair of finder switches when an instrument circuit is closed and a source of current supply for said circuits.

12. In an automatic telephone exchange system, the combination with a plurality of instrument circuits, switching mechanisms for establishing a connection between an incoming instrument circuit over which a call has been initiated and another outgoing called circuit, of a source of ringing current, a ringing circuit leading to the outgoing called circuit, switching mechanism arranged in said circuit comprising terminals, a movable contact element coöperating therewith, mechanism for advancing it successively into engagement with said terminals to intermittently despatch said ringing current, and a source supplying current for talking purposes to said instrument circuits.

13. In an automatic telephone exchange system, the combination with a plurality of instrument circuits and switching mechanisms for establishing a connection between an incoming instrument circuit over which

- a call has been initiated and another outgoing called circuit, of a source of ringing current, a ringing circuit leading therefrom, switching mechanism interposed in said circuit for intermittently interrupting the flow of ringing current comprising sets of terminals arranged in said circuit and other terminals located between said sets, a movable contact element and means for advancing it progressively, a circuit leading from one side of the ringing circuit to the last mentioned terminals forming a shunt around the generator for drawing residual current from the ringing circuit during the interruption in the flow of current therein, and a source of supplying current for talking purposes to said instrument circuits. 10
14. In an automatic telephone exchange system, the combination with a plurality of instrument circuits and switching mechanism for establishing a connection between an incoming instrument circuit over which a call has been initiated and another outgoing called circuit, of a source of ringing current, a ringing circuit leading therefrom, a switching mechanism interposed in said circuit for intermittently interrupting the flow of ringing current comprising sets of terminals arranged in said circuit and other terminals located between said sets, a movable contact element and means for advancing it progressively, a circuit leading from one side of the ringing circuit to the last mentioned terminals forming a shunt around the generator for draining residual current from the ringing circuit during the interruptions in the flow of current therein, and a source supplying current for talking purposes to said instrument circuits. 20
15. In an automatic telephone exchange system, the combination with a plurality of instrument circuits and finder and connector switching mechanisms for placing one circuit in condition for communication with another, normally open ties adapted to be closed to join said communicating circuits, a ringing circuit normally connected to said ties, a source of ringing current therein, of a switching mechanism interposed in said circuit for intermittently interrupting the flow of current therein, of a relay for closing said ties, a circuit therefor and means controlled by the ringing switch for energizing said circuit alternately with the interruptions of the ringing current, and a source of current supply for talking purposes for the instrument circuits. 30
16. In an automatic telephone exchange system, the combination with a plurality of normally open instrument circuits, a finder and connector switching mechanism, the former being adapted to pick up a calling circuit and extend it to the latter and the connector switch being adapted to select a called circuit, of a switching relay operated when the finder switch has performed its operation, a ringing circuit connected to the called circuit having open contacts therein, a ringing relay controlling said contacts which is rendered operative by the switching relay when the connector switch has performed its operation, and a source supplying current for talking purposes to said instrument circuits. 40
17. In an automatic telephone exchange system, the combination with a plurality of normally open instrument circuits, finder and connector switching mechanisms, the former being adapted to pick up a calling circuit and extend it to the latter and the connector switch being adapted to select a called circuit comprising operating mechanism, of a switching relay actuated when the finder switch has performed its operation to render the operating mechanism of the connector switch active, a ringing circuit connected to the called circuit having open contacts therein, a ringing relay controlling said contacts, a circuit therefor having two sets of openings one of which is closed by the switching relay the other being closed when the connector switch has performed its operation, and a source supplying current for talking purposes to said instrument circuits. 50
18. In an automatic telephone exchange system, the combination with a plurality of normally open instrument circuits, finder and connector switching mechanisms, the former being adapted to pick up a calling instrument circuit and the latter to select a called instrument circuit, ties between the switches adapted to connect said calling and called circuits having normally open contacts, a cut-through relay controlling said contacts, of a ringing circuit, a switching mechanism interposed in said circuit for alternately interrupting the flow of current therein and energizing the cut-through relay, a holding circuit for the latter, and means for retaining it in energizing condition when a called circuit is closed. 60
19. In a telephone exchange system, the combination with a plurality of instrument circuits, a plurality of switches serving said circuits, said switches being arranged in groups, each group being adapted to connect a calling instrument circuit with a called instrument circuit, means for distributing successive calls to different groups of switches, of busy signaling apparatus for each of said groups, said apparatus being normally inoperative, and bonds between the switches for rendering said apparatus active when a called circuit is selected by the switches of one group active when said called circuit has been previously selected by the switches of another group. 70
20. In a telephone exchange system, the combination with a plurality of instrument

circuits, a plurality of switches serving said circuits, said switches being arranged in groups, each group being adapted to connect a calling instrument circuit with a called instrument circuit, of apparatus for despatching a busy signal to a calling instrument circuit over any group of switches which is normally inoperative and is rendered active when two or more different groups of switches connect different calling circuits with the same called circuit.

21. In a telephone system, the combination with subscribers' lines, of means for establishing connections between said subscribers' lines, a source of ringing current automatically applied to the called subscriber's line, means to periodically apply said ringing current, and means to short-circuit the called subscriber's line after each ringing interval.

22. In an automatic telephone exchange system, the combination with a plurality of instrument circuits, switches serving said circuits and adapted to connect one, a calling circuit, with another, a called circuit, said switches being divided into groups, apparatus for distributing calls originating at the same time over different groups of switches, of apparatus embodying electromagnetic devices for returning over calling circuits a busy signal, trunking circuits connecting them with the several groups of switches, means for rendering said apparatus active when two instrument circuits are connected by one group of switches, other means for rendering it active when a second group of switches establishes a connection with either of the two previously connected instrument circuits.

23. In an automatic telephone exchange system, the combination with a plurality of instrument circuits, switches serving said circuits and adapted to connect one, a calling circuit with another, a called circuit, said switches being divided into groups over which connections are successively established, of a busy test apparatus associated with each group of switches comprising electromagnetic mechanism adapted to despatch over the instrument circuits a busy signal, trunking connections between the apparatus of the different groups of switches by means of which one or another of them is rendered active when one group of switches connects an instrument circuit to either of the two instrument circuits previously connected by another group of switches.

24. In an automatic telephone exchange system, the combination with a plurality of instrument circuits, a plurality of switching mechanisms serving said circuits each comprising terminals therefor, contact elements co-operating therewith and means for advancing the latter, said switches being di-

vided into groups, the different groups being arranged to establish successive connections between different instrument circuits at different times, additional terminals on said switches and other contact elements co-operating therewith and movable with the first mentioned elements, of a busy test apparatus comprising electromagnetic devices arranged to despatch a signal over the instrument circuits, circuits connecting the devices with said other terminals by means of which they are rendered active and the busy signal is despatched when the contact elements of a switch of one group engages the terminals of an instrument circuit the corresponding terminals of which have been previously engaged by the contact elements of a switch of another group and a source of current supply for said circuit.

25. In an automatic telephone exchange system, normally-open subscribers' lines arranged in groups, switching devices including a distributor for each group and trunk circuits less in number than the subscribers' lines, electromagnetic devices associated with each line to start the switching mechanism associated with each line to start the switching mechanism associated with its group when the line is closed and to cause said line to be connected to one of said trunk circuits and cause said distributor to automatically advance successively to engage different trunk circuits when a preceding trunk circuit has been selected.

26. In a telephone system, the combination with subscribers' line circuits, of automatic switching means including a connector switch for establishing connection between said subscribers' lines, a source of ringing current automatically applied to the called subscriber's line when said connector switch is connected to the line terminals thereof, of means to periodically apply said ringing current, and means to short-circuit the called line after each ringing interval.

27. In a telephone system, the combination with automatic switching means including a connector switch, stationary and movable contacts associated with said connector switch, means for controlling said switching means by interruptions in the calling subscriber's line circuit, busy back signaling apparatus, and means operable to automatically apply a busy signal to the calling subscriber when the called subscriber hangs up his receiver.

28. In a telephone system, the combination with automatic switching means including a connector switch, of stationary and movable contacts associated with said connector switch, means to control said connector switch by interruptions in the called subscriber's line circuit, a relay that is maintained energized during said line interruptions, a second relay energized and con-

trolled by the operation of said first relay, busy signal apparatus, and means controlled by said relays to automatically apply said busy signal to a calling line if the movable 5 contacts of the connector switch engage the terminals of a busy line.

29. In a telephone system, the combination with subscribers' lines, of automatic switching means to establish a connection between 10 a calling and a called line, a characteristic signal, electromagnetically operated means, and means operable by said electromagnetic means to transmit said signal to the calling subscriber when the called subscriber hangs up his receiver.

30. In an automatic telephone system, the combination with subscribers' lines, of automatic switching means to establish a connection between a calling and a called line, a characteristic signal, electromagnetically 20 operated means, means operated by said electromagnetic means to transmit said signal to the calling subscriber when the called subscriber hangs up his receiver, and means operated to restore the line of the called subscriber to its normal condition.
